UNITED STATES PATENT OFFICE.

EDWARD A. STIGGINS, DECEASED, LATE OF BEVERLY, MASSACHUSETTS; BY MARGARET B. STIGGINS, EXECUTRIX, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR WORKING UPPERS OVER LASTS.

Application filed July 14, 1916, Serial No. 109,306. Renewed September 16, 1922. Serial No. 588,731.

To all whom it may concern:

Be it known that EDWARD A. STIGGINS, late of Beverly, in the county of Essex and State of Massachusetts, deceased, invented 5 certain Improvements in Machines for Working Uppers Over Lasts, of which the following description, in connection with the accompanying drawings, is a specification, like reference characters on the drawings indicating like parts in the several 10 figures.

This invention relates to the manufacture of boots and shoes and more particularly to a machine for working an upper 15 into position upon the last over which the shoe is made. In conforming the upper materials to the requirements of the last, it has been usual to assemble the upper materials on the last and then subject the upper materials to an operation known as "pulling over" prior to and distinct from the step 20 known as "lasting." This preliminary pulling-over operation has been done by hand, and then the pulled-over shoe, as it may be termed, has been subjected to the lasting 25 operation. Recently a machine has come into extensive use for performing the preliminary operation of "pulling over" automatically, and a further development of this 30 machine has been devised wherein both the pulling-over and lasting operations have been automatically performed.

One of the objects of "pulling-over" is to properly position the upper materials on 35 the last. The tip line, for instance, in some shoes is to extend transversely of the last at a predetermined angular relation to the median line of the shoe. In others, it may be desirable to vary its angular transverse 40 position as well as its distance from the end of the toe as required by the size and style of the shoe itself. These and other considerations dictate that the shoe be so positioned in the machine during the pulling-over operation that the attendant or 45 operative may have directly in his line of vision the top of the forepart of the shoe so that he may readily examine the position of the upper on the last and make necessary 50 corrections. After the shoe has been "pulled over," it is to be subjected to the lasting operation. This is best performed when the

sole of the shoe is presented to the view of the attendant or operative, in order that he may see that the edge of the upper is properly laid upon the sole of the shoe. During 55 the lasting operation, the upper is secured in overlaid or lasted position, and in order that the fastening means may be properly applied, it is desirable that the shoe be sustained by some kind of a support. This is 60 particularly the case when the fastening devices or parts thereof require to be driven into the shoe. An important feature of the 65 present invention comprises a novel combination of shoe positioning means and pulling-over and lasting means, the construction shown comprising shoe supporting means for sustaining the shoe in position for the pulling-over operation with the toe 70 of the shoe pointing in such direction that the top of the forepart of the shoe is in full view of the operative, and movable from such position to the lasting position to cause the toe of the shoe to point in another direction 75 with the sole uppermost.

This feature of the invention is capable 80 of various embodiments, but as herein exploited, the shoe is sustained for the pulling-over operation with the toe pointing upwardly, and is movable from such position into a more nearly horizontal position with the toe pointing at an angle to the vertical and with the sole uppermost. In this 85 disposition of parts the operative has before him and directly in his line of vision in his normal working position during the pulling-over operation, the upper materials of the shoe, the edge of which he is enabled to place within the jaws of the grippers, 90 and he can adjust the upper and tip line intelligently in accordance with the shoe requirements. On the other hand, when the shoe support is moved to lasting position, the location of the shoe is so changed that 95 the shoe is presented sole uppermost for the convenient performance of the lasting operation. This movement of the shoe support to carry the shoe between the pulling-over and lasting positions may be effected 100 in various ways, either by hand or power, but in the present embodiment of the invention such movement is effected by power-operated devices. This manner of moving

the shoe support has special advantages in the present embodiment of the invention because while the invention in its broadest aspect contemplates any kind of pulling-over and lasting means, either hand or power-operated, they are herein shown as automatic means for effecting their respective functions, and in such organization an automatic movement of the shoe support is 10 preferable.

Where the operations of pulling-over and lasting have been heretofore attempted in one machine, either the operations themselves have been performed by hand, or if 15 performed by automatic means, the shoe has not been shifted to present it in the best positions for the respective operations by a movable shoe support. An important feature of the present invention, therefore, consists in a shifting shoe support for carrying the shoe between positions where the pulling-over and lasting operations are automatically performed.

It has been customary where the shoe has 20 been pulled over automatically or by power, to secure the upper in pulled-over position by means of tacks and then transfer the pulled-over shoe to another machine for the lasting operation. In the present invention the lasting means and other parts are so 25 combined and arranged that there is no longer any necessity for tacking the upper in pulled-over position after the automatic action of the pulling-over means, and in this 30 respect an important feature of the present invention consists in a novel combination of pulling-over means and lasting means with means for retaining the upper in pulled-over position for the operation of 35 the lasting means, the construction shown comprising means for moving the shoe from the pulling-over position to the lasting position while the upper is still held by the pulling-over means and for causing an end 40 embracing pad to wipe the upper about the toe as the shoe moves into lasting position and to hold the upper materials when released by the pulling-over means and for the lasting operation. This effect may be 45 secured in various ways, but in the present 50 embodiment of the invention the shoe support is mounted to turn about a transverse axis so that as the toe of the shoe approaches 55 lasting position the upper materials about the toe are wiped upwardly by the pad of the lasting devices.

In the broader aspect of the invention, the 60 lasting devices may be of any suitable character and the upper materials may be secured in lasted position by any of the usual means employed for this purpose. Another 65 important feature of the invention, however, consists of a novel means movable about the end of the last for working the upper into lasted position. In the illus-

trated embodiment of the invention for this purpose, this novel means comprises a lasting tool or element movable about the toe end of the shoe. The lasting element in the present instance comprises a wheel which 70 is arranged to travel about the toe end with its peripheral portion overlying the edge of the last. It may also be arranged to be rotated during such traveling movement. To accommodate the lasting wheel to the varying 75 thickness of stock as it rolls bodily about the toe and to conform its path of travel to slight variations in the contour of the toe, it is yieldingly supported.

An important feature of the present invention consists in novel means for lasting the entire end portion of the shoe about the toe from substantially the ball line at one side to the ball line at the opposite side. Shoes differ, however, in length from the 80 toe to the ball line on opposite sides of the shoe, and some shoes are more nearly straight along one side from the toe to the ball line than along the other side. Another important feature of the invention, 85 therefore, consists in means for changing the path of the lasting tool to cause it to travel a greater distance along one side of the shoe than the other to effectively over-work the upper into lasted position on 90 rights and lefts and on varying styles of shoes. In order to secure for the lasting wheel this varying range of travel along opposite sides of the toe the initial or starting position of the lasting wheel at one side 95 of the shoe is changeable at will, and its finishing position at the opposite side is determined by the operative during the operation of the machine.

The lasting wheel acts upon the upper 100 materials to carry the edge portions thereof into overworked relation with the bottom of the shoe and this is most effectively secured when the lasting wheel is inclined to the plane of the last bottom. The degree of 105 angular or inclined relation of the lasting wheel and shoe bottom depends upon the character of materials being overworked and other considerations; and another important feature of the invention consists in 110 means for changing this angular or inclined relation at will to suit the conditions of the work.

When the upper materials are overworked 115 in lasted position, they are secured in place. 120 This may be done in various ways, as by driving tacks through the upper material into the sole of the shoe. In the present instance, however, the lasting wheel is provided with a peripheral groove adapted to 125 accommodate a fastening wire which may be laid in said groove about the lasting wheel. One end of the wire may be anchored to the shoe at one side by a tack, so that as the upper materials are over- 130

worked by the lasting wheel, the wire will be laid against the overworked stock and finally its opposite end may be secured to the other side of the shoe and thus effectually 5 secure the upper in lasted position.

Another important and novel characteristic of the construction shown is that both ends of the shoe are lasted and secured in lasted position. In the present embodiment 10 of the invention, when the shoe is carried from pulling-over to lasting position, the heel portion of the shoe moves longitudinally and downwardly into a heel-band which acts upon the counter to lay the upper 15 smoothly about the heel portion of the last.

In the broader aspect of the other features of the present invention, the heel lasting and securing means may be of any character. The present invention, however, 20 templates important, novel characteristics in the preferred heel lasting means, which consist in automatically overworking the heel end of the upper materials and securing them in lasted position. The overworking means is constructed and arranged to travel about the heel of the shoe and wipe the upper materials inwardly step-by-step during its travel. During the action of the heel lasting means the heel portion of the 30 shoe and the upper extending about the heel are held firmly in the heel band. It is an important feature of the invention to give the heel overworking means a series of successive inward and sidewise movements to 35 plait the surplus stock over the heel bottom as the overworking means travels bodily about the heel from one side to the other. From the fact that the heel of a shoe is not usually a true circle, the path described 40 by the heel overworking means may be that of a curtate cycloid.

These and other features of the present invention, including novel pulling-over mechanisms and various details of construction and combinations of parts will be 45 herein described in connection with the accompanying drawings which show one good practical form thereof, it being understood that the invention in its broader aspects is not restricted to the particulars of the means 50 illustrated, which are susceptible of various changes and modifications within the true scope of the invention as defined by the claims.

55 In the drawings:—

Figure 1 is a front elevation of a machine embodying the present invention, some of the parts being broken away to show elements beyond;

60 Fig. 2 is a side elevation of the same machine, showing the position of the shoe and pulling-over means during the pulling-over operation;

65 Fig. 3 is a view similar to that of Fig. 2 with the shoe supported in lasting position;

Fig. 4 is a general plan view of the machine with the parts shown in the position of Fig. 3;

Fig. 5 is a sectional plan view taken on the line 5—5 of Fig. 3; 70

Fig. 6 is a front view in detached detail of parts of the toe-lasting means;

Fig. 7 is an enlarged side elevation of the pulling-over frame and connected parts showing their relations when the shoe is in 75 lasted position;

Fig. 8 is a sectional detail of the side pulling-over gripper jaws;

Fig. 9 is a view similar to that of Fig. 7 but showing some of the parts in section 80 and others broken away to disclose details beyond;

Fig. 10 is an enlarged detached detail on the line 10—10 of Fig. 9 showing the relative adjustment of the shank grippers for different widths of shoes; 85

Fig. 11 is a sectional detail on the line 11—11 of Fig. 9;

Fig. 12 is a detached plan view of certain features of the shank grippers, showing 90 their adjustment for width and swing of different lasts;

Fig. 13 is an end view of the shank gripper mechanism looking from the toe end of the shoe, parts being broken away and others in 95 section;

Fig. 14 is a detail showing one of the shank grippers when the upper is in pulled-over position;

Fig. 15 is a detail in plan view of one of 100 the shank gripper-operating connections;

Fig. 16 is an enlarged side elevation, partly in section, of the toe-lasting means;

Fig. 17 is a plan view of the toe-lasting means, some of the parts being broken away 105 and others omitted for clearness of illustration;

Fig. 18 is a plan view showing more particularly the toe rest and toe pad;

Fig. 19 is an end view of the toe pad 110 and its adjusting means;

Fig. 20 is an enlarged sectional detail of the means for controlling and changing the path of travel of the lasting wheel;

Fig. 21 is a fragmentary front view of 115 the rack and pinion adjustment shown in Fig. 20;

Fig. 22 is a front elevation showing the toe-lasting means in starting position at the side of the shoe;

Fig. 23 is a similar view of the heel-lasting means;

Fig. 24 is a plan view of the machine similar to that of Fig. 4, but with the pulling-over frame and parts carried thereby 125 omitted in order to more clearly show the toe and heel-lasting means;

Fig. 25 is a plan view of parts of the heel-lasting means showing more particularly the operative connections of certain parts; 130

Fig. 26 is a longitudinal vertical sectional view of the heel-lasting means, showing also the association of the tacking devices therewith;

Fig. 27 is a plan view partly in section, of the tacking means for securing the heel portion of the upper in lasted position;

Fig. 28 is an end view of the tacking means;

10 Fig. 29 is a view showing the shoe in lasting position and the relative positions occupied by the grippers of the pulling-over means; and

15 Fig. 30 is a diagrammatic view showing the action of the heel-lasting means as it wipes the upper over the heel portion of the shoe during its bodily traveling movement about the heel.

The main frame of the machine may be 20 of any design suitable for supporting the operating parts, and in the present instance it comprises the side frames 1 tied together by the spacing cross-frames 2. The driving shaft 3 supports fast-and-loose members 4 and 5, the adjacent friction faces of which 25 constitute clutch members under control of the operative or attendant, by means of a treadle 6 pivoted at 7 and connected by a link 8, Figs. 2 and 3, to a wedge 9. The

30 loose member 5 may be constantly driven by any suitable means, and in the present instance it is formed as a loose pulley which may be appropriately belted to the driving power. A spring 10 normally acts to separate 35 the fast-and-loose members 4 and 5, the construction being such that upon depression of the treadle 6 the fast-and-loose members may be operatively connected to impart rotary movement to the driving shaft and

40 upon release of the treadle the driving connection between the clutch members may be interrupted to permit the machine to come to rest. Connected to the driving shaft are the several means for effecting the automatic 45 pulling-over and lasting operations so that by depression or release of the treadle, the operative may at will start, continue, or interrupt the pulling-over or lasting operations and thus be enabled to inspect the

50 shoe, adjust the position of the upper upon the last, or make any corrections either in the pulled-over or lasted position of the upper materials.

The pulling-over and lasting means are 55 preferably driven from the driving shaft by means of cams provided with appropriate cam paths to carry into effect the intended purpose. In the present instance of the invention, a cam shaft 11 is extended 60 transversely of the machine frame and supported in bearings 12, 12, Fig. 5. Secured to the cam shaft 11 is a worm wheel 13 engaged by a worm 14 secured to the driving shaft 3, the construction being such that 65 upon rotation of the driving shaft, the cam

shaft will be rotated but at a reduced speed and the cams thereon be given appropriate movement, as will more fully appear.

During the pulling-over operation it is desirable that the shoe be so positioned 70 that the operative may have a full and unobstructed direct view of the shoe upper in order that he may determine at a glance if the upper and tip line of the shoe are properly positioned on the last and if not, 75 that he may readily make any desirable corrections. It is equally desirable that when the shoe is to be lasted it be presented to him with the bottom of the shoe uppermost in order that he may note the action of the 80 lasting means, the overworked position of the shoe upper, and see that the upper is properly secured in lasted position before removing the shoe from the machine. The present invention, therefore, contemplates 85 supporting the shoe in one position for the automatic operation of pulling-over and then transferring it to and supporting it in another position appropriate for the automatic lasting operation, and a good practical means to these ends will now be described.

Each side member of the main frame is provided with a part 15 to which is pivotally connected at 16, the head frame 17, 90 Figs. 1, 2 and 3, which for identification will be termed the pulling-over frame, because it has mounted thereon the pulling-over grippers and other elements of the pulling-over mechanism. Rigid with the 95 pulling-over frame is a toothed segment 18, Figs. 1 and 3, the teeth of which engage corresponding teeth in a toothed segment 19 pivoted at 20 to the machine frame and having a pin or roll 21 which engages the cam 100 path 22, Fig. 5, of a cam 23 secured to the cam shaft 11, the construction being such that upon rotation of the cam shaft 11, the cam path 22 acting upon the toothed segment 19 will cause the pulling-over head 110 17 to move about its pivotal connection with the main frame into the pulling-over position as indicated in Fig. 2, or into lasting position as indicated in Fig. 3 according to the direction of movement of the toothed 115 segment 19 as prescribed by the cam 23.

The shoe to be treated is supported for movement with the pulling-over frame between the pulling-over and lasting positions. Various detail forms of shoe supports will 120 readily suggest themselves, but in the present instance of the invention, the pulling-over frame has a bracket or jack arm 24, Fig. 7 to the projecting end of which is connected a last-pin-socket-engaging-member 125 25. The member 25 has a pin 26 for engaging the pin socket of the last and is connected to the arm 24 by a stud 27 which passes through a socket 28 of the member 25 and by frictional engagement therewith 130

normally holds the pin 26 in any position to which it may be moved. To support the shoe against the updraw action of the pulling-over means, the pulling-over frame has 5 connected to it, one or more sole rests to be further described, which engage the bottom of the shoe on the shoe support. To place a shoe on the shoe support, the member 25 is lowered and turned frontwardly or toward 10 the toe of the shoe in Fig. 7. The pin 26 is engaged with the last pin socket while in this position, and the member 25 with the shoe thereon is then turned and raised to place the bottom of the shoe against the sole 15 rests.

The pulling-over frame 17 is provided with bearings 29, which support the rock-shaft 30, Figs. 1, 4 and 7 from which extends the toe-gripper-operating arm 31 connected at 32, Fig. 9, to the toe gripper rod 33. Extending from the pulling-over frame 17 is the toe gripper bracket 34 provided at its free end with a recess or cut-out portion 35 formed with upwardly and inwardly inclined slots 36. A pin 37 rides in the slots 36 and has loosely mounted thereon one jaw 38 of the toe gripper. The other jaw 39 of the toe gripper is pivoted at 40 to the jaw 38 and has its upwardly-projecting portion 30 provided with a slot 41 which is engaged by a pin 42 connected to the actuator 43. A shoulder 44 on the jaw 39 limits the opening movement of the said jaw under the downward push of the rod 33 which is pivotally connected at 45 to the actuator 43. From the construction described, it will be apparent that when the pin 37 is at the lower or outer end of the slots 36, Fig. 2, the jaws of the toe gripper will stand open 40 beyond the toe end of the shoe ready to receive the edge of the upper material, and should the rod 33 be then pulled, its first action will close the jaws of the gripper upon the edge of the upper materials and 45 then exert a forward or toeward pull upon the upper to position the upper longitudinally of the last. This forward draw will take place about the pin 37 as an axis and when the upper ceases to yield, a further 50 pull upon the rod 33 will cause the gripper as a whole to move upwardly and inwardly in the direction of the inclined slots 36 to place the edge of the upper above and within the edge of the shoe.

55 A sole rest 46 has its sole-engaging end located to bear upon the bottom of the shoe near the toe end thereof to hold the shoe from movement responsive to the pull of the toe gripper. In the present instance the sole rest 46 is adjustably secured to the bracket or arm 34 by a bolt 47 which passes through a slot 48 in the upper part of the sole rest.

As hereinbefore noted, one aspect of the invention contemplates that the action of 60 the pulling-over means shall be automatic

and maintain the upper in pulled-over condition as the shoe is moved from pulling-over to lasting position. As one form of means for thus operating the toe pulling-over gripper, the shaft 30, Figs. 1 and 4, 70 has secured to it an arm 49 the end of which is yieldingly connected to a rod 50 which is itself joined to a toothed segment 51, Fig. 1, similar in all respects to the toothed segment 18, already described, except that segment 51 is loosely mounted on the stud 52 in axial alinement with the pivotal axis 16 about which the pulling-over frame turns for a purpose that will presently appear. 75

The toothed segment 51 is operatively engaged with a similarly toothed segment 53, Figs. 1 and 5, pivoted to the machine frame at 54, Fig. 1, and having a pin or roll 55 traveling in the cam path 56 of a cam 57 secured to the cam shaft 11, the construction 80 being such that upon rotation of the cam shaft when the parts are in pulling-over position, Fig. 2, the toe gripper will first be caused to grip the upper placed within the jaws by the operative, and then to pull 85 the upper as already described to foredraw and carry it over the shoe bottom. One reason will now be apparent why the toe gripper operating toothed segment 51 is 90 loosely mounted on its stud 52, a condition 95 that permits the segment to actuate the toe gripper as already described, under the direction of its actuating cam before the pulling-over frame commences its movement to carry the shoe to lasting position, and then 100 to move in unison with the toothed segment which operates the pulling-over frame. When the shoe has been moved to lasting position and just before the lasting means 105 acts to overwork the upper, the grippers are to let go, and the loose mounting of the toe gripper actuating toothed segment under control of its cam permits this, as will be more fully described.

In order that the toe gripper shall act 110 yieldingly upon the upper, the rod 50 is yieldingly connected to the arm 49. This is effected in the present instance by providing the rod 50 with a shoulder 58, Fig. 9, and passing the upper part of the rod through a 115 block 59 carried by the arm 49, a spring 60 being interposed between the block 59 and an adjustable nut 61 threaded to the upper part of the rod.

Side pulling-over means are provided for 120 pulling-over the upper at each side of the toe and are movable transversely in unison about a centre passing through the toe end of the last to conform them to the swing for rights and lefts and variations incident 125 to different styles of shoe.

The pulling-over frame 17, Figs. 7 and 9, carries a swing frame 62 pivoted on a stud 63, a prolongation of the axis of which 130 passes through the toe end of the shoe.

- or through the toe grippers when the latter have pulled-over the upper. In the present instance the stud 63 which affords the axis about which the swing frame 62 moves, Fig. 9, is mounted between the parts 17^a and 17^b of the pulling-over frame to give the desired stability, and the swinging end portion 64 of the frame 62 travels in an appropriate groove 65 formed in the pulling-over frame. 5 The means for moving the swing frame to the right and left for right and left shoes or different styles of shoes will presently be described.

Adjustably mounted on the swing frame 62 at each side thereof adjacent its pivotal connection with the pulling-over frame, is a bracket 65*, Fig. 7, the adjustment of the bracket in the present instance being afforded by the bolts and slots 66, Fig. 7, whereby 15 the longitudinal position of the bracket on the swing frame may be adjusted.

Pivottally mounted on each bracket 65* at 67 is a side gripper arm 68, the lower portion of which is connected to the side 25 gripper, the construction being such that should the arms 68 be swung about their pivotal connection 67 with the swing frame 62, the side grippers themselves will be shifted longitudinally of the shoe in a direction substantially parallel to the median line of the swing frame to thereby shift the upper and position the tip line in the desired transverse relation to the last. As one side gripper is shifted forwardly or towards 30 the toe, the other should be correspondingly shifted rearwardly or towards the heel, and vice versa. To this end each of the gripper arms 68 is provided with a slot 69, Fig. 7, which is engaged by a pin 70 eccentrically 35 arranged upon the shaft 71. A handle 72 is provided and connected to the shaft 71 to rotate it, the construction being such that by manipulating the handle 72 the side gripper arms 68 may be given movements in 40 opposite directions along the sides of the shoe toe either to properly position them to take the upper or to shift the upper about the toe of the last and place the tip line in desired angular relation to the median line 45 of the shoe.

Each of the side gripper arms 68 in the present instance of the invention is provided with a yoke or collar 73, Figs. 7 and 8, through which passes the slide 74 the lower 50 portion whereof at 75 constitutes one of the gripper jaws. Pivottally mounted at 76 on the gripper jaw slide 74 is the companion gripper jaw 77, the upper end portion of which is provided with a slot 78, Fig. 8, which engages a pin 79 extending from a lug 80 secured to the side operating rod 81. In order that the side grippers may have 55 lateral movement with respect to the shoe in order to conform to different widths of lasts, the yoke or collar 73 of each of the

side grippers is elongated laterally, as indicated in Fig. 8, so that each side gripper may have a limited movement in its yoke or collar 73 in a direction transversely of the shoe toward and from the other. 70

When the gripper-operating rod 81 is moved downwardly, it is desirable that the gripper jaw slide 74 be retarded from accompanying the rod 81 until the gripper jaws 75, 77 have been properly opened by 75 the stud 79 acting in the slot 78; and conversely, when the operating rod 81 is lifted, it is desirable that the gripper jaw slide 74 be retarded from movement with the rod until the gripper jaws have firmly 80 gripped the upper materials. Various means may suggest themselves to carry into effect these purposes, but in the present form of the invention the inside portion of the yoke or collar 73 is provided with the bowed 85 spring 82 which acts frictionally against the side of the gripper slide 74 to retard its free movement and enable the jaws of the grippers to be actuated as hereinbefore described. 90

The side grippers have lateral movement together with the swing frame 62 to conform them to the swing of the shoe, in which respect they differ from the toe gripper. It is desirable, therefore, that this 95 lateral movement of the side grippers be permitted without interference with the correct action of the pulling-over operating means, and in the present invention this is effected as follows: 100

Rising from the swing frame 62 are the standards 83 in which is supported the rock shaft 84, Figs. 4 and 9. Secured to the rock shaft 84 and extending rearwardly therefrom is the lever or arm 85, the rear end 105 portion of which is provided with a stud 86 which extends from the end thereof into a slot 87 formed in a yoke 88, the said slot 87 in the yoke being in the arc of a circle, Fig. 4, the centre of which is the axis 63 110 about which the swing frame 62 turns. The yoke 88 is secured to the short studs 89 mounted in bearings 90 extending from the pulling-over frame, the construction being such that the yoke 88 may turn about the 115 axis afforded by the studs 89 to thereby turn the lever 85 about its pivotal mounting 84.

Loosely mounted on the shaft 84, Figs. 4, 7 and 9, are the side gripper levers 91, the 120 end of each of which is connected as by a ball and socket joint 92, Fig. 7, with the side gripper operating rod 81. The forward extension 93 of the lever 85 has mounted therein the rock shaft 94 carrying the eccentric pins 95 at its ends. The pins 95 are connected to sliding blocks 96 mounted in the side gripper operating arms 91, Fig. 7, the construction being such that upon rotative movement being imparted to the 125 130

shaft 94 as by means of a handle 97, Fig. 7, the side gripper arms 91 may be differentially raised or lowered relatively to each other to properly draw the upper about the 5 contour of the forepart of the last. This relative movement of the side grippers is of importance in this class of machine especially where the shoe is provided with prominent box-toe, and by relative movement 10 of the side grippers the upper material may be drawn more to one side or the other of the shoe, as circumstances dictate.

In order to operate the lever 85 and thus 15 impart to the side grippers their pulling-over movement, the yoke 88 is provided with an arm 98, Fig. 4, the end of which is yieldingly connected to the operating rod 99, Figs. 4 and 7. It is desirable that the up-draw action of the side grippers upon the 20 upper shall be yieldingly applied, and to this end the arm 98 is connected yieldingly to the operating rod 99 by means of a spring 100 interposed between a block 101 carried by the arm 98 and an adjusting nut 102, the 25 action of the parts being such that normally the spring 100 would cause the end of the arm 98 to rest upon the collar 103 on the operating rod and upon downward pull of the rod 99 during the updraw movement of 30 the upper, the spring 100 will transmit the force yieldingly to the side grippers.

The operating rod 99 is connected at 104, Figs. 2, 3 and 7, to a toothed segment 105 loosely mounted upon the main frame in 35 axial alinement with the stud 16 about which the pulling-over frame turns. The teeth of the toothed segment 105 are operatively connected to the teeth of the rack segment 106 pivoted in axial alinement with 40 the stud 20, Figs. 2 and 3, and having a roll 107 adapted to travel in the cam path 108 of cam 23 secured to the cam shaft 11, as hereinbefore described—the construction being such that upon rotation of the cam shaft 45 the toothed segment 106 will be moved in accordance with the dictates of its operating cam 108 to actuate the side pulling-over grippers when the shoe is in pulling-over position as indicated in Fig. 2, and then as 50 the pulling-over frame is turned from pulling-over position to lasting position as indicated in Fig. 3, the segment 105 will be turned in unison with the toothed segment 18, Fig. 3, which is rigid with the pulling-over frame and serves to move it between the 55 pulling-over and lasting positions, as hereinbefore already described. Similarly, when the shoe has been moved to lasting position, it is desirable that the side grippers shall 60 release the upper after the upper has been seated in and is held by the parts of the lasting means, and this is effected by the loose mounting of the toothed segment 105 and its operation through the toothed segment 65 106 and its actuating cam 108.

From the construction described with respect to the side grippers, it will be apparent that as the swing frame by which the side gripper arms 68 are carried is swung laterally to one side or the other, it will similarly 70 swing the shaft 84 on which the lever 85 is fulcrumed and cause its pin 86 to travel along the slot 87 of the yoke 88, said parts being moved about the axis 63 as a centre without disturbing the operative connection 75 between the toothed segments which actuate the side pulling-over grippers.

The toe and side pulling-over grippers thus far described may be sufficient in some cases to properly pull over and position the 80 upper on the last. It is sometimes desirable, however, to provide other grippers to act upon the upper nearer the ball line of the shoe where the contour of the last merges into the shank portion thereof. 85

These additional grippers are provided by the present invention and in conjunction with the side and toe grippers effect the pulling-over operation throughout substantially the entire forepart of the shoe. At 90 the rear of the ball line of the shoe, the edge of the sole at the inside of the shank usually turns inward more abruptly than does the edge at the outside of the shank; that is, while these two edges converge heelward 95 from the ball line, the degree of convergence at one edge is greater than at the other. This is graphically illustrated by Fig. 29, wherein a left shoe is shown in full lines, and it will be noted that between the points 100 $a-a'$ at the inside edge the inward turn or direction is more abrupt than between the points $b-b'$ along the outside edge, and the shank line, as it may be termed, extends diagonally between a' and b' . It is desirable, however, that the additional pulling-over means shall act upon the upper at corresponding points somewhat in front or toward of the shank line on both the inside and outside edge of both rights and lefts. 105 An important feature of the present invention, therefore, consists in means for shifting the additional pulling-over means for rights and lefts so that the gripper that acts to pull over the inside edge of the upper 110 shall be nearer the toe of the shoe than the gripper that acts to pull over the outside edge. This is effected in the present instance of the invention as the additional pulling-over means is bodily moved laterally 115 in changing its lateral position for rights and lefts as necessitated by the swing of the lasts. It is important, also, that the edge of the gripper jaws of the additional pulling-over means be maintained in substantially 120 parallel relation with the edge of the shoe at either side and this is effected in the present instance of the invention by turning or swinging the grippers as they are bodily moved transversely of the shoe. To accom- 125 130

modate the additional pulling-over means for the treatment of shoes of different widths, adjusting devices are provided by the present invention, as will more fully appear.

The swing frame 62 is provided with a slide 109, Figs. 9 and 11, which is mounted in suitable guideways 110 on the swing frame and is movable longitudinally with respect thereto. This slide 109 carries a bearing 111, Figs. 9 and 11, which affords proper guiding and sustaining means for the additional grippers. For convenience of reference, these grippers will hereinafter be referred to as the "shank grippers," but such term is not to be regarded as one of limitation. Extending through the bearing 111 is a sleeve 112, sustained by the bearing 111, the lower portion of which carries the cross-head 113, Figs. 9, 10 and 13, provided with the transverse slotted portion 114 in which ride the blocks 115 carrying the jaws of the shank grippers. In the present instance each of the blocks 115 has a toothed portion 116, Fig. 10, in operative engagement with a pinion 117 carried by a sleeve 118 rotatable within and relatively to the external sleeve 112, the construction being such that upon rotation of the internal sleeve 118 the pinion 117 will cause simultaneous movement of the gripper-carrying-blocks 115 towards and from each other for the purpose of adjusting the lateral separation of the shank grippers for any particular width of shoe.

The gripper-carrying-blocks 115 each have projecting therefrom a rod 119 the lower end of each of which is adapted to engage the sole or bottom of the shoe at points close to the edge of the sole and to the shank grippers and constitute a sole rest or hold down. The rods 119 are mounted in the blocks 115 for rotative movement with respect thereto for a purpose that will presently appear.

Mounted for sliding movement upon each of the rods 119 is a block or sleeve 120 which is movable transversely of the shoe in a slot 121 formed in a cross-head 122, Figs. 13 and 15. The cross-head 122 is secured to the lower end of an actuator 123 which, in the present construction consists of a rod which extends upward within the sleeve 118. Pivotedly connected to each block 120 at 124, Fig. 13, is a link 125 here shown as formed of two parallel members, which are jointed at 126 to an extension of the outer jaw 127 of the associated shank gripper. The jaw 127 is pivoted at 128 to the inner jaw member, which in the present instance is formed on the lower part of the link 129. The upper portion of each of the links 129 of the shank grippers is connected by a pin and slot connection 130 to one of two laterally-extending arms 131 which

are mounted on the rods 119 for swinging movement with relation thereto. From the construction thus far described, it will be apparent that the blocks 115 which indirectly support the shank grippers may be adjusted laterally of the shoe in the cross-head 113, and that upon upward movement of the cross-head 122 or in a direction away from the shoe the shank grippers will be caused to grip the upper. Should the shank sole rests be then held from upward movement or be given a downward movement at such time, it will be obvious that the shank grippers will first grip and then pull the upper about the last both upwardly and inwardly. The present invention contemplates as the preferred form thereof that the shank grippers and shank sole rests be simultaneously moved in opposite directions, and that such movements be hand-operated, as will now be described.

The upper portion of the sleeve 112 has secured thereto the bracket 132 from which extends the arm 133, the overhanging portion 134, Fig. 7, having pivoted thereto at 135 the lever 136, Figs. 4 and 7. The short arm of the lever beyond the fulcrum 135 is connected by a link 137 to the upper end of the actuator or rod 123, the construction being such that a downward pull upon the lever handle 136 will cause an upward movement of the actuator or rod 123 to thereby close and actuate the shank grippers and a corresponding downward movement of the sleeve 112 and cross-head 113 to thereby depress the shank sole rests. In order to conveniently adjust the lateral separation of the shank grippers and sole rests the sleeve 118 is extended beyond the bracket 132, Fig. 9, and provided with a handle 139, Figs. 4 and 7. Suitable notches 140 in the bracket segment 141 are adapted to coact with a locking pin on the handle 139 to maintain the shank grippers in adjusted relation.

When the shank grippers and their associated sole rests have been actuated as hereinbefore described, it is desirable that the sole rests shall remain in their depressed position to properly position the shoe for the lasting operation. These shank sole rests are of course located one at each side of the shoe and by their engagement with the sole or bottom of the shoe prevent any tilting movement of the shoe upon its supports while being positioned for the lasting operation. To this end, the sleeve 112 has a collar 142 secured thereto by appropriate means such as the pins 143, Figs. 9 and 11. The bearing 111 has an extension or enlarged portion 144 at one side thereof, Fig. 11, in which is supported a rock shaft 145 carrying a pawl 146 which is adapted, under the action of a spring 147, to engage the teeth 148 formed upon the collar 142, Figs. 9 and 11, 130

the construction being such that when the sleeve 112 which carries the cross-head 113 and from which project the rods 119 having at their lower ends the shank sole rests, is depressed, the pawl 146 engages with the teeth 148 on the collar and serves to hold the sleeve and perforce the sole rests in depressed position, thereby locking the shoe from any rocking movement upon its supports.

When the shoe has reached lasting position or in other words, after the shoe has been pulled-over and it has been found in position for the action of the lasting means, it is desirable that the pulling-over means shall release the upper after it has been properly engaged by the parts of the lasting means and as hereinbefore described, this is effected with respect to the toe and side grippers by the automatic action of the toothed segments which constitute their actuating means. The shank grippers, however, are released by hand and when the automatic release of the toe and side grippers is effected, the shoe then having reached lasting position and the upper being properly held by the parts of the lasting means as will more fully appear, it is desirable that the shank sole rests be released from their pressure on the sole or bottom of the shoe. To this end the shaft 145 carrying the rocking pawl is provided with a crank arm 149, Figs. 9 and 11, carrying a pin 150 the upper end portion of which is in the path of movement of an arm 151 connected to the side-gripper-actuating means, Figs. 4, 7 and 9, the construction being such that upon release of the side grippers, the arm 151 will contact with the pin 150 thereby turning the rock shaft 145 to release the pawl 146 from the ratchet teeth on the collar 142 and perforce releasing the shoe from control of the shank sole rests.

The shank grippers are thus supported by the swing frame and are movable laterally for the accommodation of rights and lefts and different styles of shoes. The slide 109 which supports the shank grippers is longitudinally movable with respect to the swing frame and the shank grippers are therefore adjusted longitudinally of the shoe to properly position the shank grippers for different sizes of shoes. The shank grippers are likewise adjustable laterally with respect to each other to accommodate different widths of shoes and as such grippers are to act upon the shank portions of the shoe or those portions of the shoe adjacent the ball line where the inward inclination or trend of the shoe edge is greater on the inside than on the outside of the shoe, the present invention contemplates means for further positioning the shank grippers as will now be described in connec-

tion with a good, practical form of this feature of the invention.

The cross-head 113 has extending therefrom in a direction towards the heel end of the shoe, a slotted arm 152, Figs. 9, 10 and 12, in which is adjustably mounted a fulcrum pin 153, Fig. 9. The pin 153 may be variously secured in position lengthwise of the arm 152, but as indicated in Fig. 9 as a good form of this feature of the invention, the pin 153 has a head 154 adapted to bear against the under portion of the arm 152 and a nut and washer 155 for clamping the pin in adjusted position. The pin 153 engages a hole 156 formed in a sliding block 157, Fig. 9. The sliding block 157 is mounted in ways 158 formed in the pulling-over frame 17, the construction being such that while the block 157 may be moved in the ways 158 to different positions in a direction generally longitudinally of the shoe, it is prevented from any lateral or sidewise movement, the construction so far described being such that the block 157 may move longitudinally of the shoe on the pulling-over frame as the shank grippers are adjusted longitudinally. Extending transversely of the sliding block 157 and rigid therewith, are the arms 159, Figs. 12 and 13, each of which is provided with a slot 160. The laterally-extending arms 131 which are mounted for turning movement upon the rods 119, Figs. 12 and 13, have extending therefrom the pins 161 which engage the slots 160 formed in the arms 159 of the block 157, the construction being such that should the swing frame 62 and perforce the shank grippers and the shank rests be moved laterally to accord with the swing of the last, the pin 153 engaging the block 157 will cause the cross-head 113 to swing about the axial centre of the rod 123 to thereby position the shank grippers and shank rests so that the shank gripper at the inside edge of the shoe will be nearer to the toe than will the shank gripper at the outside edge of the shoe.

As the grippers are thus swung into desired position relative to the edge portions of the shoe, the pins 161 will cause the jaws of the grippers to maintain substantial parallelism to the edge portions of the shoe.

When the shoe has been pulled-over it is moved from pulling-over to lasting position and prior to or at the time of the lasting operation the pulling-over means releases the upper materials that the lasting means may properly overwork the edge portions thereof. As the shoe is moved from pulling-over to lasting position, the present invention contemplates that the upper shall be given an upward wiping or rubbing action at the toe and a forwardly wiping or rubbing action at the heel end to insure proper confor-

mation of the upper materials to the contour of the last, and that when the upper materials are released by the pulling-over means they shall be held in position for the proper overworking action of the lasting means. The lasting means may act upon one or both ends of the shoe and in the present instance of the invention both ends of the shoe are lasted. It will be appropriate to first describe the toe or forepart lasting means and the movement of the shoe into relation therewith.

The main frame of the machine has secured to the inner front portions thereof the brackets 162, Figs. 1, 3 and 22, provided with trackways or guides 163 for the support and adjustment of the toe-lasting frame 164. The trackways or guides 163 are curved on an arc, the centre of which is substantially at the toe of the shoe when in lasting position, as indicated in Fig. 3, and the toe lasting frame has arms 165, Fig. 17, carrying rollers 166 adapted to engage and move in the curved trackways or guides 163, the construction being such that the toe lasting frame 164 may be appropriately adjusted in a plane passing longitudinally of the shoe substantially at right angles to the plane of the shoe bottom to place the lasting wheel to be described in proper relation to the bottom of the shoe to be lasted. The toe lasting frame is adjusted as stated, by any suitable means, which as shown, may comprise a hand-piece 167 secured to a rod 168 journaled in a part 169 of the main frame and threaded into the part 170, Fig. 16, carried by lugs 171 extending from the toe lasting frame, the construction being such that by manipulation of the handle 167 the toe lasting frame may be appropriately adjusted in the trackway or guides 163.

The toe lasting frame 164 has as part thereof, the bearing 172 and upon the upper portion 173, Fig. 16, is secured the toe rest arm 174. A toe rest 175 is adapted to support the toe portion of the shoe during the lasting operation and may be of any desired construction. As shown, the toe rest 175 comprises a part to engage the toe of the shoe and a stem 176, Fig. 16, confined to limited upward movement under the impulse of a spring 177 by means of a stop, such as the screw 178.

A toe embracing pad is sustained by the arm 174 to receive the toe portion of the shoe as the latter is moved from pulling-over to lasting position and wipe the upper materials about the toe upwardly. In the present instance, Fig. 18, the pad comprises a flexible chain or carrying member 179 and a facing 180 of some flexible material, such as leather. The ends of the pad are supported by the side arms 181 which are adjustably secured at 182 to levers 183 pivotally mounted at 184 upon the upper portion of the toe

rest arm 174. Each of the levers 183 is provided with a toothed segment portion 185 which are engaged by the worm or threads 186 of a rotatable stud or shaft 187 having a milled head 188, the construction being such that by manipulation of the head 188 by hand, the ends of the arms 181 may be swung about their pivotal points 184 towards and from each other for the accommodation of toes of different forms and widths. The central portion of the pad is sustained by lugs 189, Figs. 16 and 19, extending from the central portion of the chain 179 and engaging a flange 190, Figs. 16 and 18, on the toe rest arm. From this construction it will be apparent that the toe embracing pad may be adjusted for the reception of the toes of shoes of different widths and that as the shoe is brought into lasting position the toe embracing pad will wipe the upper materials upwardly about the contour of the last and hold them in position for the lasting operation after they have been released by the pulling-over means.

The bearing 172, Fig. 16, is provided with the hollow crank shaft 191 splined to the rotatable shaft 192 within it, as by means of a key 193, the construction being such that as the toe lasting frame is adjusted in the track-ways or guides 163, the shafts 191 and 192 may be permitted the necessary relative movement longitudinally. The crank shaft 191, Fig. 16, has shoulder portions 194 which rest upon the top portion of the bearing 172 and is provided with a crank arm 195, Fig. 16, from the outer end of which rises the bearing 196. Mounted for rotative movement in the bearing 196 is the shaft 197, the lower end of which is provided with a pinion or gear 198. Secured to the toe lasting frame about the top portion thereof is the stationary toothed member 199, Figs. 16 and 17. This stationary toothed member may be secured to the toe lasting frame by any suitable means such as the screws or bolts 200, Fig. 17, and is engaged by a wide pinion 201 carried by the crank arm 195. The wide pinion 201 is also operatively engaged by the pinion 198, the construction being such that upon rotary movement being imparted to the crank shaft 191 by the shaft 192, the crank arm or member 195 will be carried about the axis of the shaft 192, and through the gearing connections described, the shaft 197 will be turned as it is bodily moved about the stationary gear member 199.

Extending from the top portion of the bearing 196, is a table 203 so that as the bearing 196 is carried bodily about the end of a shoe in lasting position, as indicated in Fig. 16, the table will be correspondingly moved. The table 203 supports a slide 204, which may be appropriately connected to the table for movement relative thereto by

suitable guiding means, which in the present instance, comprises loose blocks 205 located between a circular bearing 206 on the table and the guideways 207 formed in the central cut-out portion of the slide, as indicated in Fig. 17, the construction being such that the slide 204 may have both a sliding and rocking movement on the table 203. To maintain the slide and table in supporting relation during the sliding and rocking movement of the slide, the latter is provided with bolts 208 which extend loosely into curved slots 209 formed in the table 203.

The shaft 197 is provided at its upper end with a crank arm 210, Figs. 16 and 17, which is connected to the slide 204 by a pin 211 passing through a suitable bearing 212 formed on the inner portion of the slide, as in Fig. 17, so that as the table is carried about the end of the shoe by the crank arm 195 and bearing 196, and the shaft 197 is turned in the manner described, the slide will move bodily with the table and in addition to such bodily movement about the end 25 of the shoe, will be given a movement longitudinally of the table by the crank arm 210, and thus cause the lasting devices, to be presently described, to travel about the end of the shoe in conformity with the non-circular 30 contour of the toe of the shoe.

The slide 204 has the downwardly-extending side portions 213, Figs. 1, 6, 16 and 17, to the lower ends of which is pivotally connected at 214 the lasting tool supporting yoke 215. A bearing or sleeve 216 is mounted in the yoke 215 and supports the shaft 217 of the lasting tool 218 which may be secured to the shaft in any preferred manner, as by means of a hub 219 detachably pinned to the shaft, Fig. 16. From this construction it will be seen that as the slide is moved bodily about the end of the shoe in the manner described, the lasting tool will be carried with it. In the present form of the invention the lasting tool comprises a wheel 218 provided with a peripheral groove 220 in which may be placed a wire or other form of fastening means. Such wire may be anchored to the shoe at one side and laid upon the overworked upper as the wheel travels about the end of the shoe, and then similarly anchored at the other end to hold the upper in overworked position.

In order that the lasting wheel may lay the upper materials more effectively in over-worked position, one aspect of the present invention contemplates that it be rotated as it travels about the shoe from the starting to finishing point. This rotative movement 55 may be such as to impart to the upper a rubbing action either in the direction of bodily travel of the wheel or in the reverse direction, or in some cases the rotary movement of the lasting wheel may be such as to avoid rubbing action altogether. Any or all of

these operations are selectively within control by simply changing the relative rotative and bodily movements of the lasting wheel, which may be conveniently done in the present instance by changing the relation of the gearing for rotating the lasting wheel on its axis, as will presently appear.

Secured to the toe lasting frame and rigid therewith is a toothed member 221 of non-circular form and approximating the general contour of the toe end of the average shoe, and in operative engagement therewith is a gear or pinion 222 secured to the lower portion of the tool shaft 217, the construction being such that as the shaft and tool are carried about the end of the shoe, the lasting tool will be rotated, and the speed of rotation relative to the bodily movement about the shoe may be made to suit the desired purpose by altering the relation as to size or number of teeth of the stationary toothed member 221 and the gear or pinion 222.

The gear or pinion 222 is preferably on a hub 223 supported by the yoke 215 and is splined to the shaft 217 to permit the latter to move longitudinally without disturbing the operative relation of the gear 222 and fixed member 221. Secured to the shaft 217 is a grooved collar 224, Fig. 16, the groove of which is engaged by a pin or roll 225 carried by one arm 227 of a bell crank lever secured to the rock shaft 226 mounted on the yoke 215, the other arm 228 of said lever being normally under the action of a spring-pressed plunger 229, the construction being such that the shaft 217 and perforce the lasting wheel are normally held down yieldingly that the lasting wheel may accommodate itself to the thickness of stock as it overworks the latter to lasting position to raise the lasting wheel from operative position the shaft 226 is provided with a hand lever 230.

Mounted on the slide 204 is a plunger 231, the end of which presses against the lasting tool shaft and a spring 232 normally acts through the plunger to press the lasting tool inwardly over the shoe bottom. Each of the plungers 229 and 231 may be provided with adjusting means for varying the yielding action thereof.

When a shoe is being moved to lasting position, it is desirable that the lasting tool or wheel 218 be moved out of the way to enable the shoe to be moved into upward wiping contact with the toe embracing pad, and to this end there is mounted in lugs 233 rising from the slide 204, a short rock-shaft 234, Fig. 16, carrying a crank arm 235 adapted to engage a lug 236 projecting from the bearing 216 of the lasting tool shaft. A handle 237 secured to the rock-shaft 234 serves to remove the lasting tool from operative position at any time desired,

and against the action of the spring-pressed plunger 231.

The toe lasting means receives its operative movement from a suitable source of power transmitted through the shaft 192, Fig. 16, and in order that the shaft may move with the toe lasting frame as the latter is adjusted in the vertical plane passing longitudinally of the shoe and about the toe end of the shoe as a centre, it is connected to its source of power by flexible means. In the present instance, the shaft 192 is connected by a universal joint 238 to an intermediate shaft 239, which is itself operatively joined to a driven shaft 240, Figs. 2 and 3, by a universal joint 241, the construction being such that rotary movement imparted to the shaft 240 will be transmitted to the shaft 192, and the latter be free to accommodate itself to the adjusted positions of the toe-lasting frame.

The shaft 240 has mounted thereon a pinion 242, the teeth of which are engaged by the corresponding teeth of a sliding rack-bar 243, movable in suitable guides 244 on the main frame, Figs. 2, 3 and 5. The rack-bar 243 has teeth 245 which are operatively engaged by corresponding teeth 246 of a toothed segment 247, Fig. 2, mounted to swing about a centre at 248 on the machine frame. From this construction it will be apparent that rocking movement of the toothed segment 247 about its pivotal mounting 248 will impart to the rack-bar 243 longitudinal reciprocating movements, and perform rotary movements to the shaft 192 first in one and then in the other direction to thereby cause the toe lasting means to travel about the toe of the shoe from one side to the other and back again and perform the lasting operation.

The lasting operation at the toe end of the shoe may and usually will be completed by one travel of the lasting tool about the end of the shoe. The contour of the sole edge along the inside of the toe end of a shoe differs usually from the contour of the sole edge along the outside of the shoe, so that the length of shoe to be lasted on the inside edge differs from the length to be lasted on the outside edge. An important feature of the present invention, therefore, consists in means for changing at will either the starting or stopping points of the lasting tool or both, to accord with the length of shoe to be lasted at opposite sides, as will now be described.

Between the teeth 246 and pivotal point 248, the toothed segment 247 is provided with a longitudinally extending slot 249, Fig. 2, in which is mounted a block 250 adapted to be moved to different positions thereon. Pivotedly supported at the lower part of the machine frame is a swinging arm 251, Figs. 2, 20 and 21, likewise pro-

vided with a longitudinal guideway for a block 252, Figs. 1 and 3. The blocks 250 and 252 are connected for relative rocking movement by a pivot or pin 253, the construction being such that while the blocks 250 and 252 and their connecting pin 253 operatively connect the toothed segment 247 and swinging arm 251, the said blocks may be adjusted together in a direction longitudinally of the toothed segment and swinging arm. The swinging arm 251 has at its upper portion a pin or roller 254, Figs. 2, 3 and 5, which engages a cam track 255 in a cam 256, Fig. 5, secured to the cam shaft 11, the construction being such that upon operation of the cam shaft, the swinging arm 251 will be rocked upon its pivotal connection with the machine frame and impart similar movement to the toothed segment 247, the amplitude of which will depend upon the position of the connecting blocks 250 and 252. It will also be obvious that by changing the position of the connecting blocks between the toothed segment 247 and the swinging arm 251, the initial or starting position of the lasting tool will be correspondingly changed.

Owing to the difference in the length of shoe to be lasted at opposite sides of the toe, it is sometimes desirable to not only change the initial or starting point of the lasting tool, but to change the length of its travel so that it may finish the lasting operation on the opposite side of the shoe at a point further from or nearer to the toe than the initial or starting point. The present invention secures this result by providing means which may be effective during the operation of the machine for changing the finishing point of the lasting tool.

Referring more particularly to Figs. 20 and 21: The swinging arm 251 is mounted in a suitable bearing 257 and is provided with a groove or guideway extending longitudinally of the arm 251 in which is slidably mounted the rack-bar 258, the upper end whereof is connected to the sliding block 252, Fig. 2. The lower toothed portion 259 of the rack-bar is operatively engaged by the teeth of a pinion 260, the construction being such that by rotation of the pinion, the rack-bar may be raised or lowered to correspondingly alter the position of the connecting blocks 250 and 252 in their respective arms 247 and 251.

The pinion 260 is carried by a shaft 261, Figs. 20 and 21 which is extended through the hub portion 262 of the swinging arm 251. The outer portion 263 of the pinion shaft 261 has keyed thereto a worm 264 of coarse pitch, which is held from longitudinal movement with respect to the shaft 263 by suitable means. In the present instance such means comprises a cap 265 overlying the outer end of the worm 264 and held to the

shaft by a screw bolt or pin 266, the opposite end portion of the worm bearing against the end of the hub 262.

Mounted on the worm 264 is a sleeve 267 provided with a groove 268 which is engaged by a roll or pin 269 carried by arms 270 of a lever 271 pivotally mounted at 272 on a suitable lug 273 projecting from the side of the machine frame. The sleeve 267 has secured thereto a pin 274 which extends through a suitable opening or hole in a fixed collar, 275, preferably clamped to the bearing 257 by means such as the clamp bolt 276 the construction being such that as the sleeve is moved longitudinally by the lever 271, it is prevented from rotating. Secured within the sleeve 267 is a bushing 277 having a spiral 278 corresponding to and engaging the worm 264, the construction being such that upon movement of the sleeve 267 and its bushing longitudinally of the worm the latter and the pinion shaft to which it is keyed will be caused to rotate and performe raise or lower the block connection between the toothed rack 247 and swinging arm 251.

It will be noted that the adjustment of the connecting blocks 250 and 252 may be made at any time by means of the hand lever 271, so that the initial or starting point of the lasting tool may be adjusted to the proper position before starting the automatic action of the machine, and during the operation of the machine the blocks may be adjusted to lengthen or shorten the travel of the lasting tool to its finishing position. Thus the toe ends of shoes of different sizes, different styles, and rights and lefts of the various sizes and styles may be lasted, and if during the lasting operation, the operative should desire to inspect or adjust the work before proceeding further, he has simply to remove his foot from the treadle 6, whereupon all automatic action of the machine ceases.

In the broad aspect of the invention, the lasting means may be confined to one end portion of the shoe, as for instance, the forepart; yet in another aspect, the invention contemplates heel end lasting means as well as the forepart lasting means. The general purposes of the invention may be carried into effect in connection with the pulling-over means by any suitable character of lasting means, either at the toe or heel end of the shoe or at both ends. In the present instance, however, heel lasting means of novel and important character are employed as will now be described. Where both heel and toe lasting means are used relative suitable adjustment of the two towards and from each other is desirable, and in the present instance of the invention such adjustment is provided for the heel lasting means for moving it into proper relation with the fore-

part lasting means for lasting shoes of different sizes.

The heel lasting means in the present invention is contrived to overwork the upper into lasted position by a tool which travels about the heel of the shoe. As shown, this tool takes the form of a wiper movable bodily about the heel portion of the shoe and operated in a manner to lay the edge of the upper over the bottom of the shoe by successive operations as it is bodily moved. Suitable securing means are provided, and as here shown are moved about the heel to properly drive suitable fastenings through the edge of the upper as the latter is wiped or overworked into lasted position. The various novel features of the heel lasting means and their operations will now be described as embodied in one good practical form thereof.

The machine frame has secured thereto the trackways 280, Figs. 1 and 23 extending longitudinally towards the forepart lasting devices in which are received the rollers 281 connected to the lugs 282 projecting from the heel end lasting frame 283, Figs. 25 and 26, the construction being such that the frame 283 may be moved towards and from the forepart lasting means to suit shoes of different lengths. For conveniently effecting this adjustment the frame 283 has secured thereto at 284 one end of an adjusting device, shown as a screw 285, Fig. 26, on which is threaded the bevel gear 286 held from longitudinal movement with the screw by suitable means such as a casing 287 secured to a fixed part 288 of the main frame, Fig. 24.

Mounted in suitable bearings 289, Fig. 24, is a transverse shaft 290 carrying a bevel pinion 291 meshing with the bevel gear 286, said shaft 290 being operated through the bevel gears 292 and 293, the latter of which is secured to a shaft 294 mounted to turn in suitable bearings 295 and actuated at will by the hand crank 296. From this construction it will be apparent that the heel end lasting frame may be adjusted towards and from the forepart lasting means to suit the size or length of the shoe being lasted.

The frame 283 has a heel receiving portion 297, Fig. 26, to which is secured as by the screws 298, the circular guide 299 having guideways 300 extending in circular arcs about the heel receiving portion 297 of the heel lasting frame. Mounted in the bearings 301 of the heel lasting frame is the shaft 302 bored to receive the operating shaft 303 which is splined thereto, as at 304, the construction being such that as the heel lasting frame is adjusted back and forth the operative relation of the shafts 303 and 302 will remain undisturbed. Secured to the bored shaft 302 to rotate therewith is a gear or pinion 305, the teeth of which are engaged

by the teeth of the wheel 306, Figs. 25 and 26, secured to the lower end of a shaft 307 mounted in the heel lasting frame 283. The upper end of the shaft 307 is provided with 5 a pinion 308, the teeth of which engage the teeth of the segment 309. The segment 309 is connected to or formed as part of a traveling frame 310 having lips or flanges 311 which engage the circular guideways 309 formed in the circular guide 299, the construction being such that upon rotation of the shaft 308 in one or the other direction, the traveling frame 310 will be carried in a circular path about the heel portion of a shoe 10 placed within the recess of the guide 299. In order that the amplitude of traveling movement of the frame 310 by the segment 309 may be sufficient for the frame to pass from one side of the heel to the other without unduly enlarging the portion of the segment, the shaft 307, and gears 306 and 308 are duplicated, one set being placed on each side of the segment, so that as the toothed segment leaves the teeth of one gear or pinion 308 it will pass into operative relation with the other. This may not always be necessary, but it affords a compact means for getting the desired movement of the segment and traveling frame without unduly extending the tooth portion of the segment.

The traveling frame 310, Fig. 26, has extending from it the table 312 which indirectly supports the heel lasting means. Mounted upon the top of the table 312 is the 35 slide 313 which may be confined to such sliding movement with respect to the table 312 at one end as by means of the screw-pin or bolt 314 which passes loosely through a slotted portion 315 of the table and is connected to the slide 313 preferably by adjusting means such as the adjusting right and left threaded bolt 316.

Mounted for rotative movement on the traveling member 310 is a shaft 317 which 40 preferably has a bearing at its lower portion in the tooth segment 309, Fig. 26, and at its upper portion in the table 312. The shaft 317 has a crank-arm 318 from which projects a crank-pin 319 engaged with a suitable opening in the slide 313 mounted upon the table top. In order that the shaft 317 may be slowly turned as the traveling frame 310 is moved about the heel portion of the shoe and thus cause the slide 313 to move inwardly at the side portions of the heel and outwardly at the rear portions of the heel, said shaft 317 is provided with a sprocket wheel 320, Figs. 25 and 26, which is connected by a sprocket chain 321 to a 45 similar sprocket wheel 322 on a rotatable shaft 323 carried by an arm 324 extending as a crank arm from the top portion of the bored shaft 302. The shaft 323 just described, is provided with a pinion 325 on its lower end which is driven from a stationary

gear 326, there being interposed between them an idle gear 327, Fig. 25, the construction being such that as the shaft 308 is rotated and through the connections described carries the traveling frame 310 and the 50 crank-arm 324 about the heel-receiving portion 297 of the heel lasting frame, the shaft 317 is slowly rotated and through its crank-pin 319 gradually traverses the slide 313 inward or outward, thus modifying the circular movement imparted to the slide 313 by the traveling frame 310 and causing the said slide to move about the heel portion of the shoe in a path substantially the same as the contour or outline of the heel of the 55 shoe.

Mounted upon the slide 313 is a wiper carrier 328 carrying a wiper 329 which is appropriately secured thereto. The wiper carrier 328 is provided with an elongated slot 330 which receives the upper end portion of the crank pin 319 as indicated in Fig. 26. The wiper carrier 328 has a bearing portion 331 through which passes the shaft 332 provided with an eccentric portion 333 which is received in a circular bearing portion 334 of the slide 313, the construction being such that as the shaft 317 is rotated in the manner hereinbefore described, and as it carries the slide 313 inwardly at the 60 sides of the shoe and outwardly at the end thereof, it likewise carries the wiper carrier 328 and the shaft 332 and its eccentric portion 333.

It is desirable, however, that as the wiper 100 performs its wiping function to lay the upper materials over the bottom of the shoe, it be given a frontward and sidewise wiping action in order to properly plait the upper over the heel portion where it is full, and 105 this effect is produced by imparting to the shaft 332 a rotary movement as will now be explained. Mounted upon the shaft 322 is a sprocket wheel 335 about which passes the sprocket chain 336, Figs. 25 and 26. The 110 sprocket chain 336 is also engaged by the large sprocket wheel 337 mounted on the upper end of the shaft 338 carried by the bearings 339 extending upward from the crank arm or frame 324. At its lower end 115 the shaft 338 carries a pinion 340 the teeth of which are in operative engagement with the teeth of a stationary internally-toothed gear 341, Figs. 25 and 26, which may be appropriately secured as by bolts 342 to the 120 heel lasting frame 283. Inasmuch as the shaft 332 will be bodily moved towards and away from the heel as it is carried about the heel, the sprocket chain 326 is made sufficiently slack to permit such movement, and 125 is maintained in operative relation with the respective sprocket wheels 335 and 337 by a yielding arm 343 in the nature of a belt-tightener. Said arm 343 is mounted upon the top portion of the bearing 339 as indi- 130

cated in Fig. 26, and carries at its end a roller 344 which bears upon the exterior portion of the sprocket chain 336, a spring 345, Fig. 26, having one end secured to the 5 arm 343 and the other to an arm 346 and acting normally to move the roller in a direction to take up the slack in the sprocket chain 336, the construction being such that as the wiper carrier 328 is moved about the 10 heel portion of the shoe from one side to the other, it is caused to follow a path of movement substantially in accordance with the outline of the heel portion of the shoe, and during such path of movement, the 15 wiper itself is given a forward and side-wise wiping action to properly wipe the upper over the bottom of the shoe substantially as indicated by the diagram in Fig. 30. In this diagram the shoe to be 20 lasted is represented at 347. The eccentric 333 is represented by the large series of circles at the outside of the diagram. The shaft 332 is represented by the smaller circles within the larger circles 333 and to 25 the shaft 332, as represented by the circles in the diagram, is connected the wiper carrier 328. The double series of circles between the heel of the shoe and the exterior large circles 333 in the diagram represent the shaft 317 and to 30 its eccentric pin 319. It will be noticed that the eccentric pin 319 engages the slot 330 in the wiper carrier 328 through the interposition of a suitable block 348, Fig. 30. As the wiper carrier 328 is moved about the heel portion of the shoe from one side to the 35 other, the crank pin 319 as shown in the diagram, Fig. 30, gradually moves from an inner to an outer position relative to its shaft 317, thereby moving the slide 313 40 which carries the wiper carrier outwardly as the wiper carrier passes around the end of the shoe. In other words, the shaft 317 makes substantially one revolution as it is carried about the end of the shoe by the carrier frame 310, while the shaft 332 carrying the eccentric portion 333 makes one revolution at each tack driving station, thereby imparting to the end of the wiper a movement generally represented diagrammatically by the long dash lines in Fig. 30 along 45 one side of the heel portion of the shoe. Thus, it will be noted that as the heel lasting device or wiper is bodily carried about the heel portion of the shoe in a path corresponding generally to the outline of the 50 heel of the shoe, it will also be given an inward and sidewise wiping action to properly lay the upper in plaits upon the bottom of the heel, the wiper being presented, moreover, in substantially the same angular relation to the different successive portions of the edge of the shoe bottom.

When the shoe has been pulled over and it is carried by the shoe-supporting means 55 from pulling-over position to lasting posi-

tion, the present invention in its broad sense contemplates that the heel portion or counter of the upper shall be wiped forwardly or toeward as the heel portion of the shoe is placed into operative relation with the heel lasting means. To this end there is mounted upon the heel receiving portion of the guide 299, Figs. 25 and 26, a flexible heel pad. In the present form of the invention these comprise a chain 349 lined with suitable non-abrasive material such as leather or the like 350. The chain is carried at each end by the arms 351 which are adapted to swing inwardly about their pivotal mountings 352 and may be adjusted with respect thereto by suitable adjusting means such as the screws 353. When the shoe is moved into lasting position it is carried bodily from the pulling-over position in a direction to seat the heel portion of the shoe 55 within the heel pad by a movement of the shoe in a direction substantially longitudinally. In the present illustrated form of the invention this is effected by turning the pulling-over frame and the shoe supporting 60 means which is carried thereby about an axis 16, Fig. 3, extending transversely of the shoe and preferably somewhat beyond the heel portion thereof, the construction and movements of parts being such that as the heel of the shoe passes into the heel pad the latter will wipe the upper or counter of the shoe about the heel towards the toe and retain the same in position for the action of the heel lasting means.

Hereinbefore was described an appropriate means for supporting the shoe and for shifting the shoe from pulling-over to lasting position. It should be stated at this time that in addition to supporting the shoe 105 by engagement with the last pin socket of the last which constitutes the primary shoe supporting means, as employed in the present instance of the invention, the sole portion of the shoe is engaged by suitable 110 sole rests 46 at the toe and 119 at the side portion of the shoe, as hereinbefore described. In addition to such sole rests, it may be desirable in some cases to employ a heel sole rest 354 which may be suitably 115 secured to the pulling-over frame and have its lower end 355 located to engage the bottom of the shoe or sole thereof when the shoe is held by its primary supporting means in pulling-over and lasting position. 120 During the pulling-over operation the shoe-supporting means such as described, will be sufficient to hold the shoe in position with the upper presented to the view of the operative, and the sole rests already described 125 will maintain the last from movement or hold it stationary while the pulling-over means is positioning the upper thereon.

The present invention, in addition to the heel lasting means described, also contem- 130

plates that the upper materials about the heel shall be secured in lasted position when they have been overworked by the heel lasting means, and any suitable securing means 5 may be employed for this purpose. In the present instance, however, the securing means for the heel portion of the shoe consists of tack-driving means. To withstand the blows of the tack driver in driving tacks 10 into the heel portion of the shoe, the shoe-supporting means hereinbefore described has at its end portion a projection 356, Fig. 7, adapted to engage and ride upon the sustaining shelf 357 suitably connected to the heel-lasting frame 283, Fig. 26. This rest may be 15 variously formed, and as shown, comprises a sleeve portion 358 on the top of which the shelf 357 is formed, said sleeve portion being telescopically mounted in a suitable supporting socket 359 projecting from the heel-lasting frame 283. A stiff spring 360 mounted 20 between the sleeve 358 and the bottom of the supporting socket 359 may effectively serve to sustain the heel supporting means when 25 the shoe is brought to lasting position and by yielding movement of the spring permit the movement of the shoe to such position readily and without binding of parts. A 30 limiting stop 361 may be provided to engage an opening in the sleeve 358 to limit its movement under the impulse of the spring 360.

Hereinbefore it has been noted that the shaft 303 telescopically connected to the 35 bored shaft 302 imparts operative movement to the heel lasting means, and it is appropriate at this time that the means for operating the shaft 303 be described. The shaft 303 is connected by a universal joint 362, Figs. 40 2, 3 and 26, to a connecting shaft 363, which at its lower end is connected at 364 to the upper end portion of a shaft 365, Figs. 2, 3 and 5, mounted in suitable bearings in the machine frame. The shaft 365 carries at 45 its lower end a pinion or gear 366, the teeth of which are adapted to engage corresponding teeth in a sliding rack bar 367 in a manner similar to that already described for operation of the toe-lasting means. The 50 rack bar 367 has other teeth 368 which are operatively engaged by the teeth of the segment 369, said segment being carried by an arm 370, Fig. 2, pivoted at its upper end at 371 to the machine frame. The arm 370 is 55 provided with a slot 372 in which is adjustably mounted a block 373, Figs. 2 and 5, connected by means similar to the means hereinbefore described for operating the toe-lasting means to a pin or roll 374 which 60 travels in the cam path 375 of a cam 376 secured to the cam shaft 11, the construction being such that as the cam shaft is rotated, the arm 370 carrying the toothed segment 369 will be rocked about its fulcrum and im-

part to the rack-bar 367 longitudinal reciprocating movements and perforce, to the shaft 303 the desired rocking movements first in one and then in the other direction.

In one aspect of the invention, the securing means for securing the upper in lasted position about the heel of the shoe may be of any appropriate character, but the present invention likewise includes novel and important means for securing the upper in lasted position about the heel of the shoe. 70 In this respect the invention provides that when the wiper has overworked the upper to lasting position, it shall be clamped hard upon the work at the time the securing means or tack is driven into the work, and as one convenient means for securing this end, the tack driving means is instrumental in moving a part to hold the wiper hard upon the work at the moment the tack or fastener is 75 driven.

Mounted upon the wiper carrier 328, Fig. 26, is a frame 377 which primarily supports a tack-supplying means and the tack-driving means as will now be explained. The shaft 332 at its upper portion carries a worm 378 which is operatively engaged with a worm wheel 379, the shaft 380 of which carries a sprocket wheel 381 which is connected to a similar sprocket wheel on a shaft 382, Fig. 26, by means of a sprocket chain as 80 indicated in Fig. 26, or other suitable connections, the construction being such that as the worm 378 is rotated by the shaft 332, the shaft 382 will be rotated to properly agitate the tacks within the usual hopper 383, 85 and cause them to be fed properly to the raceway 384 as usual in this class of devices.

Mounted in a suitable casing 385 supported by an appropriate bracket 377 is the tack driving bar 386, to the upper end of which is connected by the nuts 387, a cap or collar 388 which may be suitably lined with leather or other flexible material to take up the severity of the shock when the driver bar 105 reaches its lowest position. The driver bar 386 is raised by an arm 389 pivoted on the shaft or stud 390, Figs. 26, 27 and 28, one end of which arm connects with the driver bar 386 as indicated in Fig. 26, and the other end 391 of which is depressed against the tension of the driving spring 392 by means of a cam 393 mounted on the shaft 332, the construction being such that upon rotation of the shaft 332 the arm 389 will be raised 110 to lift the driver bar 386 and then release the driver bar to the action of the driving spring 392.

When a tack is to be driven it is separated from the remainder of tacks in the raceway 125 by a separator 394 pivoted at 396 and having an end portion to be engaged by a cam 397 mounted to rotate with the shaft 332.

This tack separator 394 has a slotted portion 398 which receives a tack from the raceway as the separator is moved and positions it for the driver. When the tack is taken 5 from the raceway by the separator, it is desirable that the end of the tack be held above the work to not interfere with the movement of the work under the tack by engagement therewith; and to this end the present 10 invention provides the tack holders 399, Figs. 26 and 27, pivoted at 400 and having toe portions 401 which are normally under the influence of spring-pressed plungers 402, the construction being such that the holders 15 399 which are located above the lasting wiper will yieldingly hold a tack taken from the raceway by the separator and will themselves be forced apart by the driver as it comes down and drives the tack, thus releasing the tack to the full driving operation of the driver.

As hereinbefore noted, it is desirable that the wiper 329 be forced downward upon the work after it has overworked the upper to 25 lasting position, and during the driving of a fastener. To this end the casing 385 in which the driver bar 386 is operated has an incline or cam upper portion 403 between which and the cap 388 secured to the top of 30 the driver is interposed a rotatable sleeve 404 having a similar cam or incline portion to contact with the incline 403 of the casing, the construction being such that as the driver comes down and hits the rotatable 35 sleeve or collar 404, the latter is turned, and this turning movement of the sleeve or collar is utilized in clamping the wiper upon the work. In the present instance of the invention this is effected through the rack 40 teeth 405 secured to the sleeve or collar 404 and engaging with the teeth of a sliding rack bar 406, Fig. 28. The teeth of the rack bar are made sufficiently wide to present a toothed portion to the teeth 405 in all positions of the sleeve or collar 404. Pivottally 45 connected to the rack bar at 407, Fig. 28, is a lever 408, the lower portion of which is pivoted to the bracket 377 at 409 and has a projecting portion 410 provided with teeth 50 411. The teeth 411 of the angle lever 408 are engaged with similar teeth of a slide 412, Fig. 28, the lower end portion of which is connected at 413 by suitable means such as the bolt as shown, to an upwardly-projecting portion 414 of the wiper 329, the construction being such that when the driver bar descends to drive a tack, the sleeve or collar 404 will be rotated by the impact of the cap 388 and caused to turn to thereby 55 move the rack bar 406 to the left, Fig. 28, and clamp the wiper 329 firmly upon the work. As the driver bar is lifted immediately after the tack or fastener is driven, the spring action of the wiper 329 will cause

a reverse movement of the angle lever 408 65 and its connected rack 406 sufficient to permit the wiper to release its firm pressure upon the upper materials as it is withdrawn for its next overworking stroke.

From the construction described it will be 70 apparent that the fastener driving devices are movable with the wiper and serve to present a tack or other fastening in proper position relative to the end of the wiper to secure the upper materials in lasted position 75 after each successive overworking action of the wiper.

When a shoe is to be pulled-over and lasted, it is mounted on the shoe support and the action of the pulling-over means is made 80 effective when the upper of the shoe is presented to the full view of the operative. The shoe is then shifted from the pulling-over position while the pulling-over means still maintain their pull upon the upper and 85 is placed in lasting position with the toe pointing in a different direction and with the sole uppermost in full view of the operative. As the shoe is moved into lasting position the heel portion of the shoe is 90 seated within the heel pad or part, and given a toeward wiping action; the upper above the forepart of the shoe is likewise given a wiping action towards the bottom of the shoe and the upper is held or clamped by 95 the wiping means. When the shoe has thus been placed in lasting position ready for the lasting operation, the pulling-over means is automatically operated to release the upper which is at this time clamped in position 100 by the toe and heel pads and the upper is thereupon overworked to lasted positions at the forepart and heel portions of the shoe, the pulling-over means remaining substantially in the lasting position during the 105 lasting operation. In lasting shoes, it is generally sufficient for the lasting means herein described to make one movement about the end of the shoe to be lasted. It is convenient, therefore, and usually desirable 110 to start the action of the lasting means at one side of the end of the shoe and stop its lasting action at the opposite side. The position of parts as indicated in Fig. 24 graphically illustrates the starting position 115 both of the forepart and the heel lasting means; and as will be obvious, the stopping position of these parts will be opposite the sides of the shoe from the starting positions. If, during the pulling-over or lasting operations, or either of them, the operative finds it desirable to stop the machine to examine the work, or manually adjust any of the parts, he has simply to remove his foot from the treadle and the machine comes to rest. After the desired adjustment has been made, 120 depression of the treadle will at once start the machine at the part in the cycle of its 125

operation where it was stopped, and continue its operation as long as the treadle remains depressed.

What is claimed is:—

- 5 1. In a machine of the character described, the combination of shoe supporting means, pulling-over means organized and arranged to pull over a shoe while held by the supporting means in one location, lasting means for lasting an end of the shoe while sustained by the supporting means in another location in which it is tipped lengthwise from its first location to cause the toe to point in a different relation to the horizontal, and connections between the machine frame and shoe supporting means permitting the shoe to be shifted from pulling-over to lasting position.
- 10 2. In a machine of the character described, the combination of pulling-over means, shoe supporting means for supporting a shoe with the toe pointing in one direction for the action of the pulling-over means, lasting means for lasting the toe end of the shoe while sustained by the said supporting means, and means for shifting the shoe supporting means from pulling-over to lasting position to cause the toe of the shoe to point in a different direction.
- 15 3. In a machine of the character described, the combination of pulling-over means, shoe supporting means for sustaining the shoe in one position for the action of the pulling-over means, and lasting means for lasting a shoe while held in another position by the supporting means, said shoe supporting means being constructed and arranged to permit the shoe to be shifted in a plane extending longitudinally of the shoe from pulling-over to lasting position to cause the toe of the shoe to point in a different direction.
- 20 4. In a combined pulling-over and lasting machine, pulling-over means, shoe supporting means for sustaining the shoe with the toe directed upwardly during the operation of the pulling-over means, and lasting means for lasting the end of the shoe while still on the said shoe supporting means, said shoe supporting means being adapted to be shifted after the pulling-over operation to place the shoe in position for lasting with the toe of the shoe pointing in a different direction.
- 25 5. In a combined pulling-over and lasting machine, the combination of pulling-over mechanism arranged to pull-over a shoe in a position in which the operative in his normal working position may see the upper face of the forepart of the shoe, lasting mechanism arranged normally supported substantially in its operating plane and to operate on the shoe in another position in which the sole is uppermost, and a shoe support adapted to sustain the shoe independently

of the pulling-over mechanism and movable to carry the shoe from pulling-over position into operative relation with the lasting mechanism.

6. In a machine of the class described, the combination of pulling-over means for acting upon a shoe when in one position, lasting means for acting upon the shoe when in another position, and automatic means for shifting the shoe from one position to the other, said automatic shifting means including a shoe support and sole rest for sustaining the shoe during the action of the pulling-over and lasting means.

7. In a machine of the class described, the combination of means for pulling-over a shoe, lasting means for lasting an end of the shoe in a different position, shoe supporting means for sustaining a shoe in both its pulling-over and lasting positions, and automatic means for moving the shoe supporting means between said two positions.

8. In a machine of the character described, the combination of means for pulling-over a shoe when in one position, means for lasting the shoe when in another position, shoe supporting means for sustaining the shoe independently of the pulling-over and lasting means, and automatic means for operating the pulling-over and lasting means and for moving the shoe supporting means to carry the shoe from one position to the other.

9. In a machine of the character described, the combination of means for pulling-over a shoe, a shoe support for sustaining the shoe independently of the pulling-over means with its toe directed upwardly during the pulling-over operation, means for lasting the end of a shoe when supported in another position, and automatic means for moving the shoe support from the pulling-over to the lasting position.

10. In a machine of the character described, the combination of pulling-over means, shoe supporting means for supporting a shoe independently of the pulling-over means with the toe pointing upwardly for the pulling-over operation, and lasting means for lasting the end of the shoe, said shoe supporting means being movable from pulling-over position to present and support the shoe bottom uppermost with the toe pointing in a different direction for the action of the lasting means.

11. In a machine of the character described, the combination of means for pulling-over a shoe, a shoe support for sustaining the shoe independently of the pulling-over means in pulling-over position, lasting means, and automatic means for shifting the support and pulling-over means from the pulling-over position to the lasting position and for releasing the pulling-over

means and maintaining said means substantially in the lasting position during the lasting operation.

12. In a machine of the class described, 5 the combination of power means for pulling-over a shoe, lasting means for lasting the shoe, a shoe support for supporting the shoe in one position independently of and for the action of the pulling-over means 10 with the toe pointing in one direction, and automatic means for shifting the shoe supporting means to another position and for supporting the shoe for the action of the lasting means with the toe pointing in another direction.

13. A shoemaking machine having, in combination, pulling-over means arranged to pull-over a shoe in a position with the upper of the shoe in the view of the operative, lasting means arranged to operate on the shoe when it is in a position with the sole in the view of the operative, a shoe support for sustaining the shoe in both pulling-over and lasting positions and shiftable between pulling-over and lasting positions, and automatic means for causing the pulling-over means to pull-over the shoe, move with the shoe to lasting position, release the upper, and be returned to pulling-over position after the shoe has been lasted.

14. In a machine of the class described, pulling-over means for acting on the shoe in one position with the toe pointing in one direction and the shoe upper presented to the operative, lasting means for lasting the shoe in another position with the toe pointing in a different direction and with the bottom of the shoe presented to the operative, and shoe supporting means for independently supporting the shoe in pulling-over and lasting positions and adapted to be shifted to carry the shoe from pulling-over position into operative relation to the lasting means.

15. In a machine of the class described, the combination of means for pulling-over a shoe in a position with the toe pointing in one direction, lasting means for lasting the shoe in a position with the toe pointing in another direction, and a shoe support for supporting the shoe in position for engagement by the pulling-over means and movable about an axis extending laterally of the shoe to carry the shoe from pulling-over position to lasting position.

16. In a machine of the character described, the combination of pulling-over means, end lasting means including a pad to engage the end of the shoe, and shoe shifting means for shifting the shoe from pulling-over position to lasting position and causing the pad to wipe the upper about the end of the shoe as it is shifted into lasting position.

17. In a machine of the character de-

scribed, the combination of pulling-over means organized to pull over a shoe, lasting means for lasting the heel of the shoe, and shoe shifting means adapted to shift the shoe from pulling-over position to lasting 70 position in a direction to cause the heel lasting means to wipe the upper about the heel of the shoe.

18. In a machine of the character described, the combination of pulling-over means organized to pull over a shoe, lasting means for lasting the heel and forepart of the shoe, and shoe shifting means for shifting the shoe from pulling-over to lasting position in a direction to cause the heel 75 lasting means to wipe the upper forwardly about the heel of the shoe and the forepart lasting means to wipe the upper towards the bottom of the shoe as it is shifted to lasting position.

19. In a machine of the character described, the combination of pulling-over means organized to pull over a shoe, lasting means for lasting the heel and forepart of the shoe, and a shoe support for independently supporting the shoe in pulling-over position and adapted to shift the shoe from pulling-over position to lasting position in a direction to cause the heel-lasting means to wipe the upper about the heel of 90 the shoe and the forepart lasting means to wipe the upper about the forepart of the shoe.

20. In a machine of the character described, the combination of pulling-over means organized to pull over a shoe, lasting means for the heel and forepart of the shoe including a heel pad and a toe pad, and means for shifting the shoe from pulling-over to lasting position and seating the ends 100 of the shoe in the heel and toe pads.

21. In a machine of the character described, the combination of an end gripper, means for automatically closing said gripper upon the edge portion of the upper and subjecting the upper to a toeward pull, and means acting under the impulse of the toeward pull to move the gripper inward over the bottom of the shoe when the upper resists further toeward movement.

22. In a machine of the character described, the combination of a toe end gripper, means for causing the said gripper to grip the edge of an upper and then subject the upper to a toeward pull, and means acting under the impulse of the toeward pull when the upper resists further toeward movement to carry the gripper and the edge of the upper in a direction over the bottom of the shoe while the gripper maintains its 110 pull upon the upper.

23. In a machine of the character described, the combination of shoe-supporting means, pulling-over means to act upon the upper about the toe of a shoe sustained by 120 130

said supporting means, shank pulling-over means at opposite sides of the shoe to act upon the upper adjacent the front portion of the shank, and means for relatively shifting the shank pulling-over means at the opposite sides of the shoe in opposite directions longitudinally of the shoe to conform them to the shape of the shoe.

24. In a machine of the character described, the combination of pulling-over means organized and arranged to pull-over the upper about the toe portion of the shoe, automatic means for operating the pulling-over means, and other manually-operated pulling-over means for manually pulling-over other portions of the shoe.

25. A machine of the character described, comprising in combination, power-operated pulling-over means for pulling the upper about the toe portion of a shoe, manually-operated pulling-over means for pulling the upper at other portions of the shoe, and means for shifting the manually-operated pulling-over means at opposite sides of the shoe relatively in opposite directions longitudinally of the shoe.

26. A machine of the character described, comprising pulling-over means for pulling-over the forepart of the shoe, means for swinging said pulling-over means laterally for different swings of shoes, and means acting as they are swung to relatively move the pulling-over means at opposite sides of the shoe about a common centre in opposite directions longitudinally of the shoe.

27. A machine of the character described, comprising pulling-over means for pulling-over the forepart of the shoe, means for swinging said pulling-over means together laterally for different swings of shoes, means acting as they are swung to relatively move the pulling-over means at opposite sides of the shoe in opposite directions longitudinally of the shoe, and means for changing the angular relation of the pulling-over means as they are swung laterally.

28. A machine of the character described, comprising grippers to grip and pull the upper at opposite sides of the shoe, means for moving the grippers together transversely of the shoe about a common centre to conform their positions to the lateral swing of different shoes, and means for simultaneously moving the gripper at one side of the shoe nearer to the toe and the gripper at the opposite side further from the toe as the grippers are moved transversely together.

29. A machine of the character described, comprising grippers to grip and pull the upper at opposite sides of the shoe, means for moving the grippers together transversely of the shoe to conform their positions to the lateral swing of different shoes, means for simultaneously moving the gripper at one side of the shoe nearer to the toe and the

gripper at the opposite side further from the toe as the grippers are moved transversely together, and means for changing the angular relation of the grippers to the median line of the machine as they are so moved. 70

30. A machine of the character described, comprising grippers to grip and pull the upper at opposite sides of the shoe, means for moving the grippers together transversely of the shoe about a common centre 75 to conform their positions to the lateral swing of different shoes, means for simultaneously moving the gripper at one side of the shoe nearer to the toe and the gripper at the opposite side further from the toe as the grippers are moved transversely together, and means for adjusting the gripper for different sizes of shoes.

31. A machine of the character described, comprising grippers to grip and pull the upper at opposite sides of the shoe, means for moving the grippers together transversely of the shoe about a common centre to conform their positions to the lateral swing of different shoes, means for simultaneously 90 moving the grippers about a common centre to effect movement of the gripper at one side of the shoe nearer to the toe and the gripper at the opposite side further from the toe as the grippers are moved transversely together, and means for relatively adjusting the grippers transversely for different widths of shoes. 95

32. A machine of the character described, comprising, in combination, grippers to grip and pull the upper at opposite sides of the shoe, a common support for the grippers, means for moving the support and with it the grippers in a direction transversely of the shoe, and means acting as the support for 100 the grippers is moved transversely to effect movement of the grippers at opposite sides of the shoe in opposite directions longitudinally of the shoe.

33. A machine of the character described, comprising pulling-over means for pulling-over the toe and forepart of a shoe, means for moving the pulling-over means at the sides of the shoe transversely together about an axis passing through the toe of the shoe 115 to accord with the different swing of shoes, and means for changing the angular relation of said pulling-over means at the sides of the shoe to the median line of the machine as they swung about said axis. 120

34. A machine of the character described, comprising pulling-over means for pulling-over the toe and forepart of a shoe, means for moving the pulling-over means at the sides of the shoe transversely about an axis 125 passing through the toe of the shoe to accord with the different swing of shoes, and means for simultaneously moving the pulling-over means at one side of the shoe nearer to the said axis and the pulling-over means 130

at the other side of the shoe further from said axis as they are both moved transversely.

35. A machine of the character described, comprising in its construction a support for sustaining the shoe with the toe pointing in one direction, means for pulling over the shoe, a sole rest for confining the shoe from movement on its support during the operation of the pulling over means, and lasting means, the shoe support being mounted for movement to carry the shoe to lasting position and to tip it lengthwise to cause the toe to point in a different relation to the horizontal.

36. A machine of the character described, comprising in combination, a movable shoe support for shifting a shoe from pulling-over to lasting position with the toe of the shoe pointing in a different direction, pulling-over means for pulling-over the shoe, a sole rest acting in opposition to the pulling-over means for maintaining the shoe on said support, said support and sole rest being movable for shifting the shoe from pulling-over to lasting position, and a lasting tool movable progressively about the end of the shoe along the edge of the shoe bottom for overworking the upper when the shoe is in lasting position.

37. In a machine of the general character described, the combination of pulling over means for pulling the upper of a shoe to position the upper upon the last, a sole rest for engaging the bottom of the shoe, and manual means for simultaneously moving the pulling-over means and the sole rest in opposite directions to subject the upper on the last to tension.

38. A machine of the character described, comprising in combination, grippers for gripping the upper at each side of the shoe, sole rests for engaging the sole of the shoe at each side of the centre of the shoe, and means for imparting to the grippers and sole rests substantially rectilinear movements in opposite directions for pulling the upper into position on the last.

39. A shoe-making machine having, in combination, a support for sustaining a shoe to be lasted, a lasting tool, and means for bodily progressing the lasting tool around the end of the shoe while engaged with the upper for overworking the upper into lasted position.

40. In a machine of the character described, the combination of a shoe support for supporting a shoe, a lasting tool, and means for moving the lasting tool around the end of the shoe while engaged with the upper in a path substantially conforming to the contour of the end of the shoe for overworking the upper into lasted position.

41. In a machine of the character described, the combination of means for pull-

ing the upper of a shoe, and a lasting tool movable bodily along the edge of the shoe while in contact with the upper for overworking the upper into lasted position.

42. A machine of the character described, comprising a lasting tool movable bodily along the edge of the shoe to overwork the upper into lasted position, and means for rotating the tool as it is bodily moved.

43. In a machine for working an upper into lasted position, the combination of a lasting tool, means for progressing the lasting tool bodily along the edge of the shoe to progressively overwork the upper to lasted position, and means for turning the lasting tool to cause different portions thereof to act upon the upper as it progresses bodily along the edge of the shoe.

44. In a machine for working an upper into lasted position, a rotary lasting wheel for lasting the end of a shoe, and means for bodily moving the lasting wheel about the shoe along the margin of the last bottom to overwork the upper to lasted position.

45. In a machine for working an upper into lasted position, the combination of a lasting wheel adapted to engage the upper and place it on the bottom of the shoe, and means for moving the lasting wheel round the end of the shoe for causing the lasting wheel to wipe the upper on the bottom of the shoe as the wheel travels along the edge of the shoe.

46. In a machine of the character described, the combination of a lasting tool, means for bodily moving said tool about the end of the shoe to overwork the upper into lasting position, means for causing different portions of the tool to act upon the upper as it moves about the shoe, and means for permitting the tool to conform to the varying thickness of the work as it moves over different portions of the work.

47. In a machine of the character described, the combination of a lasting tool, means for bodily moving the lasting tool along the edge of the shoe to overwork the upper into lasting position, and means permitting the tool to conform to varying thickness of work as it moves over different portions thereof.

48. A machine for operating upon a shoe, comprising in combination, a rotary lasting wheel, means for moving the lasting wheel along the edge of a shoe to overwork the upper into lasting position, and means for yieldingly holding the lasting wheel against the work as it moves over the work.

49. In a machine of the character described, the combination of a power-operated lasting wheel mounted for bodily movement along the sides and about the end of a shoe, and means for rotating the wheel as it is thus bodily moved.

50. In a machine of the character de-

130

- scribed, the combination of a lasting wheel for laying the upper over the bottom of a shoe, means for changing the angular relation of the lasting wheel to the plane of the shoe bottom, and power means for moving the lasting wheel about the shoe to lay the edge of the upper into lasting position.
51. In a machine of the character described, the combination of shoe-supporting means, a lasting tool, means for progressing the tool along the sides and about the end of a shoe to overwork the upper to lasted position, and means for changing the path of travel of the lasting tool.
52. In a machine of the character described, the combination of shoe-supporting means, a lasting tool, means for progressing the tool along the sides and about the end of a shoe to overwork the upper to lasted position, and means for causing the lasting tool to travel a greater distance along one side of the shoe than along the other side.
53. In a machine of the character described, the combination of a lasting wheel adapted to work the upper into lasted position, means for adjusting the starting point of the lasting wheel at one side of the shoe and for changing the length of travel of the lasting wheel along the other side of the shoe.
54. In a machine of the character described, means for pulling the upper to position on the last, means for clamping the upper to the last, a lasting tool, and means for moving the lasting tool about the shoe and in continuous contact with the upper while the upper is held by the clamping means to overwork the upper into lasted position.
55. In a machine of the character described, a lasting frame, a lasting tool carried by the lasting frame, means for adjusting the lasting frame to change the angular relation of the lasting tool to the plane of the bottom of the shoe, and means for progressively moving the lasting tool round the end of the shoe along the edge of the shoe in any adjusted position of the lasting frame to overwork the upper to lasted position.
56. In a machine of the character described, a lasting wheel, means for bodily moving and rotating the lasting wheel about a shoe, and means for relatively adjusting the lasting wheel and shoe about a centre passing through the toe of the shoe to change the angle at which the lasting wheel operates upon the upper to work it into lasted position.
57. In a machine of the character described, the combination of a shoe support, sole rests at opposite sides of the shoe to prevent displacement of the shoe, a lasting wheel, and means for moving the lasting wheel about the shoe from one side to the other while the shoe is held by the sole rests.
58. In a machine of the character described, shoe-supporting means, a lasting wheel adapted to work the upper into lasting position and to hold and lay a wire onto the upper as the lasting wheel overworks it into lasting position, and means for rolling the wheel over the upper while the shoe is held by the shoe supporting means.
59. In a machine for working a shoe upper into lasted position, the combination of a lasting tool, means for carrying the tool about the end of a shoe from one side to the other, and means for modifying the movement of the tool as it is carried about the shoe to conform its path to the contour of the end of the shoe.
60. A machine for working a shoe upper into lasted position, comprising in combination, a lasting tool, an actuator for moving the tool bodily about the end of the shoe, and means for modifying the movement of the tool effected by the actuator to cause the path of the tool to conform to the contour of the end of the shoe.
61. In a machine for working a shoe upper into lasted position, the combination of a lasting tool, means for rotating the tool, means for carrying the tool about the end of a shoe from one side to the other, and means for modifying the movement of the tool as it is carried about the shoe to conform its path to the contour of the end of the shoe.
62. In a machine for working the upper of a shoe into lasted position, the combination of a lasting tool, means for moving the tool about the end of the shoe from one side to the other, means for modifying the movement of the tool prescribed by the moving means to conform the path of movement to the contour about the end of the shoe, and means operable at will for removing the tool from lasting position.
63. In a machine for working the upper of a shoe into lasted position, the combination of a shoe support, a lasting wheel, means for moving the lasting wheel about the end of the shoe on said support to overwork the upper into lasted position, and means for removing the wheel from lasting position to enable the shoe to be moved into lasting position.
64. In a machine of the character described, the combination of a shoe support, a lasting wheel, means for traveling the moving wheel about the end of a shoe to overwork the upper into lasted position, spring means for yieldingly holding the lasting wheel against the work during the lasting operation, and means operable at will to lift the lasting wheel from the work.
65. In a machine of the character described, the combination of means for pulling the upper of a shoe into position on a last, means for supporting the shoe while the upper is being pulled into position on

- the last and for shifting the shoe to another position for lasting, end lasting means, and means for operating upon the upper as the shoe is shifted to lasting position to wipe 5 the upper toward about the heel and sole-ward about the toe of the last and acting to hold the upper during the lasting operation.
66. In a machine of the character described, the combination of a lasting frame 10 having a supporting table movable about the end of the shoe in a substantially circular path, a lasting tool, means interposed between the lasting tool and table for moving the tool in a direction towards and from 15 the shoe as it is carried about the end of the shoe to conform the path of the tool to the contour of the shoe.
67. In a machine of the character described, the combination of an end lasting 20 frame adjustable in a plane extending longitudinally of the shoe and about a centre adjacent the end of the shoe, a lasting tool carried by the said frame for progressively overworking the upper along the sides 25 and around the end of the shoe, and means for moving the lasting tool about the shoe in a non-circular path.
68. In a machine of the character described, the combination of an end lasting frame 30 adjustable in a plane extending longitudinally of the shoe and about a centre adjacent the end of the shoe, a lasting tool carried by the said frame for progressively overworking the upper along the sides and 35 around the end of the shoe, a crank shaft for swinging the tool about the shoe, and a crank-shaft for moving the tool towards and from its centre of swinging movement as it travels about the shoe.
- 40 69. In a machine of the character described, the combination of a lasting tool, a support in which said tool is rotatably mounted, means for moving the support about the end of the shoe from one side to 45 the other, and means for rotating the tool as it is moved about the shoe by its support.
70. In a machine of the character described, the combination of a lasting tool, a table, means for moving the table in a circular path about the end of the shoe, a slide 50 mounted on the table and carrying the lasting tool, and means for moving the slide over the table as the table is moved about the end of the shoe.
- 55 71. In a machine of the character described, the combination of a lasting tool, a table, means for moving the table in circular path about the end of the shoe, a slide 55 mounted on the table and carrying the lasting tool, means for moving the slide over the table as the table is moved about the end of the shoe, and means for moving the tool relatively to the slide away from operative 60 position to enable the shoe to be moved into lasting position.
72. In a machine of the character described, the combination of end lasting means movable along the sides and about the ends of the shoe lengthwise of the bottom edge of the shoe for overworking the upper 70 into lasted position at each end of the shoe, means for positioning the upper on the last prior to the lasting operation, and power means for operating said lasting means to last both ends of the shoe simultaneously. 75
73. In a machine of the character described, the combination of end lasting means for progressively overworking the upper at different points successively along the edge of the last bottom into lasted position 80 at each end of the shoe, means for positioning the upper on the last prior to the lasting operation, power means for operating said end lasting means to last both ends of the shoe simultaneously, and means for 85 adjusting the end lasting means relatively for lasting shoes of different sizes.
74. In a machine of the character described, the combination of means for pulling and positioning the upper on the last, 90 lasting means for overworking the upper, a shoe support for sustaining the shoe in pulling position and for shifting the last and upper from pulling to lasting position, and an additional support for sustaining the shoe 95 when in lasting position.
75. A shoe-making machine having, in combination, pulling-over mechanism and lasting mechanism, a shoe support, said pulling-over mechanism and shoe support being 100 movable to transfer a pulled-over shoe to the lasting mechanism, the pulling-over mechanism being adapted to release the shoe to the control of the lasting mechanism and remain substantially in releasing position 105 until the shoe has been lasted and then return to pulling-over position.
76. A shoe-making machine having, in combination, pulling-over mechanism for pulling-over a shoe in one position, lasting 110 mechanism adapted to travel about the shoe for lasting the shoe in another position with the toe pointing in a different direction, a shoe support for carrying the shoe from pulling-over to lasting position, and upper 115 fastening means for securing the upper in lasted position as it is lasted.
77. A shoe-making machine having, in combination, a head frame, a shoe support carried by the head frame, pulling-over 120 means for pulling-over the shoe on the shoe support while the upper is in full view of the operative, a lasting tool adapted to progressively overwork the upper into lasted position, and means for moving the 125 head frame and shoe support to carry the shoe to lasting position while under tension of the pulling-over means.
78. In a machine of the character described, the combination of end lasting 130

means comprising a wiper to wipe the upper about the end of the shoe into overworked position, and means for moving the wiper about the end of the shoe and imparting simultaneously an in and out and sidewise wiping movement thereto as it is moved about the shoe.

79. In a machine of the character described, the combination of a wiper for 10 working the upper about the end of a shoe into lasted position, means for moving the wiper bodily about the end of the shoe from one side to the other in a non-circular path to conform substantially to the contour of 15 the end of the shoe, and means for imparting to the wiper as it moves in said path a wiping action to successively work different portions of the upper into lasted position.

80. In a machine of the character described, the combination of a wiper for 20 working the upper of a shoe into lasted position, means for bodily moving the wiper along the shoe in substantial conformity with the non-circular contour of the end of 25 the shoe, and means acting automatically for imparting to the wiper a succession of wiping movements as it travels bodily along the shoe.

81. In a machine of the character described, the combination of a wiper for 30 working the upper of a shoe into lasted position, means for bodily moving the wiper along the shoe in substantial conformity with the contour of the edge of the shoe, and 35 means acting automatically to impart an in and out and sidewise wiping movement to the wiper as it moves bodily along the edge of the shoe.

82. In a machine of the character described, the combination of a wiper for 40 working the upper of a shoe into lasted position, a support for the wiper movable in a circular path to carry the wiper about the end of the shoe from one side to the other, and 45 means for modifying the movement of the wiper due to the movement of said support to cause the wiper to move in a non-circular path about the end of the shoe, and means for giving to the wiper its wiping movements to overwork different portions of the upper as it moves about the shoe in its non-circular path.

83. In a machine of the character described, the combination of a wiper for 50 working the upper of a shoe into lasted position, a support for the wiper movable in a circular path to carry the wiper about the end of the shoe from one side to the other, and means for modifying the movement of the wiper due to the movement of said support to cause the wiper to move in a non-circular path about the end of the shoe, and means for giving the wiper successive overwiping movements in a curved path as it travels 55 about the shoe.

84. In a machine of the character described, the combination of a wiper, means for moving the wiper about the end portion of a shoe, and means automatically operative as the wiper is thus moved to impart thereto 70 a succession of wiping movements as it travels about the shoe.

85. In a machine of the character described, the combination of a wiper, and connected mechanisms for moving the wiper 75 about the end portion of a shoe and for imparting thereto a succession of wiping movements in a curved path as it travels about the shoe.

86. In a machine of the character described, the combination of a wiper, means for moving the wiper about the end portion of a shoe and imparting thereto a succession of wiping movements in a curved path, as it travels about the shoe, and means for clamping 85 the wiper on the overworked upper to hold it in position for the insertion of a fastener and then unclamping the wiper to permit it to be withdrawn from overworking position. 90

87. In a machine of the character described, the combination of a wiper carrier movable about the end of a shoe and a wiper movable therewith, means for imparting a succession of wiper movements to the wiper 95 as it is moved about the shoe, a source of fastener supply movable with the wiper, and a tacker for driving a tack through the upper overworked into lasted position by the wiper. 100

88. In a machine of the character described, the combination of shoe supporting means for sustaining a shoe in stationary position, a wiper for overworking the upper into lasted position, means for moving the wiper about the end of a shoe sustained by 105 said supporting means, and means operating automatically as the wiper is moved about the shoe for giving the wiper a succession of forward and back and sidewise movements to work the upper about the end of the shoe into lasted position. 110

89. In a machine of the character described, the combination of shoe supporting means for sustaining a shoe in stationary position, a wiper for overworking the upper into lasted position, means for moving the wiper about the end of a shoe sustained by 115 said supporting means, means for giving the wiper a succession of forward and back and sidewise movements to work the upper about the end of the shoe into lasted position, and a tack driver movable with the wiper and operative to drive a tack into the shoe on successive wiping movements of the wiper. 120 125

90. A shoe-making machine having, in combination, pulling-over means for positioning an upper on the last, lasting means for simultaneously lasting both ends of the shoe, and means for causing the lasting means at each 130

end of the shoe to travel bodily about the end of the shoe to progressively overwork the upper into lasted position.

91. A shoe-making machine having, in combination, end lasting means for overworking the upper into lasted position at each end of the shoe, means for progressing the lasting means about the ends of the shoe, and means for fastening the upper in over-worked lasted position as it is progressively lasted.

92. A shoe-making machine having, in combination, lasting means for overworking the upper into lasted position at each end of the shoe, and means for moving the end lasting means at each end of the shoe from one side to the other and about the end of the shoe.

93. A shoe-making machine having, in combination, lasting means for overworking the upper into lasted position at each end of the shoe, means for moving the end lasting means at each end of the shoe from one side to the other and about the end of the shoe, and fastening means acting to fasten the upper as it is progressively overworked into lasted position.

94. A shoe-making machine having, in combination, a shoe support, and an end lasting wheel adapted to overwork the upper progressively into lasted position about the end of the shoe and apply fastening means to the upper to hold it in lasted position as the lasting wheel progressively over-works the upper.

95. A shoe-making machine having, in combination, a shoe support, pulling-over means comprising a toe gripper, means for closing the grippers upon the upper materials and imparting to the upper a forward pull, said means being constructed and arranged to cause the gripper to move upwardly and over the bottom of the shoe due to the resistance of the upper to further forward movement.

96. A shoe-making machine having, in combination, a toe end gripper for pulling-over the toe end of the shoe, side grippers for pulling-over the upper at the sides of the toe, shank grippers for pulling-over the upper adjacent the ball line, and means for simultaneously shifting the side and shank grippers different amounts laterally to conform to the swing of the shoe.

97. A shoe-making machine having, in combination, a toe gripper, a swing frame mounted to swing about an axis passing substantially through the toe of the shoe, side grippers carried by the swing frame, and means for moving said frame to conform the relation of the side grippers to the swing of the shoe.

98. A shoe-making machine having, in combination, a toe gripper, a swing frame mounted to swing about an axis passing sub-

stantially through the toe of the shoe positioned to be pulled-over, grippers mounted for lateral movement together with said swing frame to conform to the swing of the shoe, and means for turning the grippers as they are swung laterally to maintain the line of the grippers substantially parallel to the edge of the shoe.

99. A shoe-making machine having, in combination, a toe gripper, a swing frame mounted to swing about an axis passing through the toe of the shoe positioned to be pulled-over, grippers mounted for lateral movement together with said swing frame to conform to the swing of the shoe and adjustable relatively in a lateral direction, and means for turning the grippers as they are swung laterally to maintain the line of the grippers substantially parallel to the edge of the shoe.

100. A shoe-making machine having, in combination, a pulling-over frame, pulling-over mechanism carried by the pulling-over frame, a toothed segment secured to the pulling-over frame for moving it from pulling-over position to lasting position, a toothed segment connected to the pulling-over means for actuating it, and means for causing both of said segments to move in unison as the pulling-over frame is moved from pulling-over position to lasting position and to be then relatively moved to cause the pulling-over means to release the upper.

101. A shoe-making machine having, in combination, pulling-over mechanism to pull-over a shoe including grippers to act at opposite sides of the shoe adjacent the ball line, means for supporting both grippers, means for laterally shifting the gripper supporting means to effect lateral movement of the grippers together for rights and lefts, and means acting as the grippers are shifted to positively move the gripper that is to pull-over the upper at the inside edge toward and the gripper that is to pull-over the outside edge heelward.

102. A shoe-making machine having, in combination, pulling-over mechanism to pull-over a shoe including grippers to act at opposite sides of the shoe adjacent the ball line, means for laterally shifting the grippers together for rights and lefts, means acting as the grippers are shifted to move the gripper that is to pull-over the upper at the inside edge toward and the gripper that is to pull-over the outside edge heelward, and means for turning the grippers in opposite directions as they are moved toward and heelward.

103. A shoe-making machine having, in combination, pulling-over mechanisms to pull-over a shoe including grippers to act at opposite sides of the shoe adjacent the ball line, a movable unitary support for supporting both grippers, means for laterally

- shifting the gripper support to effect lateral movement of both grippers together for rights and lefts, means acting as the grippers are shifted to move the gripper that is to pull-over the upper at the inside edge toeward and the gripper that is to pull-over the outside edge heelward, said grippers being adjustable relatively for different widths of shoes.
10. 104. A shoe-making machine having, in combination, grippers to grip and pull the upper of a shoe, a sole rest at each side of the shoe, means for moving the grippers and sole rests in opposite directions to pull the upper, a lock for holding the sole rests when the grippers release the upper to prevent tilting movement of the shoe as it is positioned for lasting.
11. 105. A shoe-making machine having, in combination, grippers at each side of the shoe, a sole rest to engage the bottom of the shoe at each side thereof, means for moving the sole rests in a direction towards the shoe as the grippers pull the upper, lasting means to overwork the pulled upper into lasted position, and means for locking the sole rests to prevent tilting of the shoe as the upper passes into control of the lasting means and is released by the grippers.
12. 106. A shoe-making machine having, in combination, power-actuated grippers to pull-over one part of the shoe, hand-actuated grippers to pull-over another part of the shoe, sole rests to engage the sole at each side of the shoe as the hand-operated grippers are actuated, lasting means to overwork the upper into lasted position, a lock to hold the sole rests in engagement with the shoe when the hand-actuated grippers release the upper to prevent tilting of the shoe as it is positioned for lasting, and means actuated by the power-operated grippers to release the sole rests when the power-operated grippers release the upper.
13. 107. In a shoe-making machine, the combination of pulling-over means and lasting means constructed and arranged to operate respectively upon a shoe in different positions of the shoe, a shoe support for sustaining the shoe for the action of the pulling-over means with the toe pointing in one direction, and means for moving the shoe support in a plane passing longitudinally of the shoe to shift the shoe to lasting position with the toe pointing in a different direction.
14. 108. In a shoe-making machine, the combination of pulling-over means and lasting means constructed and arranged to operate respectively upon a shoe in different positions of the shoe, power means for operating the pulling-over and lasting means, a shoe support for sustaining the shoe for the action of the pulling-over means with the toe pointing in one direction, and means for moving the shoe support in a plane passing longitudinally of the shoe to shift the shoe to lasting position with the toe pointing in a different direction.
15. 109. In a shoe-making machine, the combination of pulling-over means and lasting means, means for sustaining the shoe in one position for the action of the pulling-over means, means for moving the shoe from pulling-over to lasting position, and additional means for supporting the shoe arranged to become effective as the shoe is moved from pulling-over to lasting position.
16. 110. In a shoe-making machine, the combination of power actuated pulling-over means, lasting means, a shoe support for sustaining the shoe in position for the operation of the pulling-over means, means for shifting the shoe support to carry the shoe from pulling-over position with the toe of the shoe pointing in one direction to lasting position with the toe of the shoe pointing in another direction, and means acting as the shoe is shifted from pulling-over to lasting position to shift the pulling-over means while maintaining operative connection between said means and its power actuating mechanism.
17. 111. In a shoe-making machine of the character described, the combination of a shoe support for sustaining the shoe in a fixed position for lasting, a lasting wheel movable along the edge portion of the shoe from one side of the shoe to the opposite side to lay the upper into lasted position, and means for positively rotating the lasting wheel as it is moved along the edge portion of the shoe.
18. 112. In a shoe-making machine of the character described, the combination of a shoe support for sustaining the shoe in a fixed position for lasting, a lasting wheel movable along the edge portion of the shoe from one side of the shoe to the opposite side to lay the upper into lasted position, means for supporting the lasting wheel in a plane diagonal to the plane of the shoe bottom, and means for positively rotating the lasting wheel as it moved along the edge portion of the shoe.
19. 113. In a machine of the character described, the combination of a shoe support for sustaining a shoe for the lasting operation, a lasting tool for laying the upper of the shoe into lasted position, and means for imparting to the tool movements about the shoe in the path of a curtate cycloid.
20. 114. A machine of the class described having, in combination, a shoe supporting jack adapted in one position to support a shoe with its sole rearward and its toe pointing upward in an elevated location substantially in front of the workman's eyes, pulling-over mechanism constructed and arranged to operate upon the shoe in such position, said jack being movable to lower the shoe

bodily to a lasting position and to swing it to a posture with its sole upward, and lasting mechanism constructed and arranged to operate upon the shoe in its lowered position.

115. A machine of the class described having, in combination, a shoe supporting jack adapted in one position to support a shoe with its sole rearward and its toe pointing upward in an elevated location substantially in front of the workman's eyes, pulling-over mechanism constructed and arranged to operate upon the shoe in such position, said jack being movable to lower the shoe bodily to a lasting position and to swing it to a posture with its sole upward by a forward and downward swinging movement about an axis substantially beneath the heel end portion of the shoe in its pulling-over position and to the rear of the shoe in its lasting position, and lasting mechanism constructed and arranged to operate upon the shoe in its lowered position.

116. A machine of the class described having, in combination, means for pulling over a shoe with its toe pointing upward and the top of the forepart substantially facing the operator's working position, means for lasting an end of the shoe when the shoe is presented in a different position bottom upward, and means for moving the shoe about an axis located substantially beneath the heel end portion of the shoe in its pulling-over position and to the rear of the shoe in its lasting position in shifting it between its different positions.

117. A machine of the class described having, in combination, means for pulling over a shoe with its toe pointing upward and the top of the forepart in view of the operator in his working position, means for lasting an end of the shoe when the shoe is presented in a lower position bottom upward, and means for positioning the shoe for the pulling-over operation, said shoe positioning means being movable with the shoe about an axis located substantially beneath the heel end portion of the shoe in its pulling-over position and to the rear of the shoe in its lasting position in shifting it between its different positions.

118. A machine of the class described having, in combination, a jack for receiving and supporting a shoe, means for pulling over a shoe supported by the jack in one position, the jack being movable to change the altitude and inclination of the shoe for lasting, and means for lasting the shoe as presented in such different position by the jack.

119. A machine of the class described having, in combination, a jack for receiving and supporting a shoe, means for pulling over a shoe supported by the jack in one position, the jack being movable about an axis extending laterally of the shoe to change the

position of the shoe for lasting, and means for lasting the shoe as presented in such different position by the jack.

120. A machine of the class described having, in combination, means for pulling over a shoe in one position of the shoe, means for positioning the shoe for the pulling-over operation, means for lasting the shoe, means for causing said shoe positioning means and pulling-over means to swing the shoe bodily downward to a lower position for lasting, and means for causing the pulling-over means to release the shoe and to remain substantially in the lasting location during the lasting operation.

121. A machine of the class described having, in combination, pulling-over means, lasting means, means for positioning a shoe for the pulling-over operation, said pulling-over means and shoe positioning means being movable together about an axis extending laterally of the shoe to present the shoe in a different posture for lasting, and means for causing the pulling-over means to release the shoe and to remain substantially in the releasing position adjacent to the shoe during the lasting operation.

122. A machine of the class described having, in combination, pulling-over means arranged to pull over a shoe with its toe pointing upward and the top of the forepart in view of the operator in his working position, means for lasting both the forepart and the heel of the shoe with the shoe presented in a different posture and the bottom of the shoe in view of the operator, and means movable to change the posture of the shoe.

123. A machine of the class described having, in combination, a pulling-over means arranged to pull over a shoe presented in a posture convenient for that operation, means for lasting both the forepart and the heel of the shoe when presented in a different posture convenient for the lasting operation, and shoe positioning means movable about an axis extending laterally of the shoe in changing the posture of the shoe.

124. A machine of the class described having, in combination, pulling-over means arranged to pull over a shoe in one position of the shoe, means for lasting both the forepart and the heel of the shoe when the shoe is presented in a different position, and shoe positioning means movable to carry the shoe from pulling-over position into operative relation to said forepart and heel lasting means.

125. A machine of the class described having, in combination, pulling-over means arranged to pull over a shoe in an elevated location with the top of the forepart in view of the operator, means for lasting both the forepart and the heel of the shoe with the bottom of the shoe facing upward and presented substantially horizontally in a lower

plane, and means for carrying the shoe from pulling-over position to present it with its bottom face in said lower plane for lasting.

126. A machine of the class described having, in combination, means for pulling over a shoe in one position of the shoe, means for lasting both the forepart and the heel of the shoe when the shoe is presented in a different position, and a shoe support movable relatively to the forepart and heel lasting means to carry the shoe from pulling-over position and to present it to said forepart and heel lasting means.

127. A machine of the class described having, in combination, a jack for receiving and supporting a shoe, means for pulling over a shoe supported on the jack in one position, the jack being movable to change the altitude and inclination of the shoe for lasting, and means for lasting both the forepart and the heel of the shoe as presented by the jack.

128. A machine of the class described having, in combination, means for pulling an upper over a last, means for lasting the forepart of the shoe, power driven mechanism for operating said pulling-over means in sequence and lasting means and for changing the posture of the shoe between the pulling-over and lasting operations, and means for clamping the upper on the last prior to the operation of the lasting means on the shoe to retain the upper in pulled-over position and permit the pulling-over means to release the shoe.

129. A machine of the class described having in combination, power operated means for pulling over a shoe in a position enabling the operator in his normal working position to view the top of the forepart of the upper, means for lasting the forepart of the shoe when the shoe is presented in a different position with its bottom face in view of the operator, shoe positioning means movable in time relation to said pulling-over means to change the position of the shoe between the pulling-over and the lasting operations, and means for clamping the forepart of the upper on the last prior to the operation of the lasting means on the shoe to permit the pulling-over means to release the shoe.

130. A machine of the class described having, in combination, means for pulling-over a shoe in one position of the shoe, means for lasting the shoe in a different position, said pulling-over means and the shoe being movable together to transfer the shoe to lasting position, and upper clamping means into operative relation to which the shoe is moved in its approach to lasting position and prior to the operation of the lasting means upon the shoe to permit the pulling-over means to release the upper before the lasting operation is performed.

131. A machine of the class described hav-

ing, in combination, pulling-over mechanism, lasting mechanism, power driven means for operating said pulling-over and lasting mechanisms, and controlling means comprising a friction clutch constructed and arranged to enable the operator to stop the machine at any point in its cycle of operations.

132. A machine of the class described having, in combination, pulling-over mechanism arranged to pull over a shoe presented in one position, lasting mechanism arranged to operate upon the shoe when presented in a different position, power driven means for operating said pulling-over and lasting mechanisms and for moving the shoe from pulling-over position to lasting position, and controlling means arranged to enable the operator to stop the machine at any point in its cycle of operations.

133. A machine of the class described having, in combination, pulling-over mechanism and lasting mechanism constructed and arranged to operate upon a shoe in succession during a continuous operation of the machine, and controlling means comprising a friction clutch constructed and arranged to enable the operator to stop the machine at any point in its cycle of operations.

134. A machine of the class described having, in combination, pulling-over mechanism arranged to operate upon a shoe when presented in a different position, and power driven means for operating said pulling-over and lasting mechanisms and for moving the shoe from pulling-over to lasting position during a continuous operation of the machine.

135. In a machine of the class described, a gripper for engaging an upper on a last, means for closing said gripper upon the upper and for operating it to pull the upper outward from the edge of the last bottom, and controlling means constructed and arranged to cause the gripper in response to the resistance of the upper in said outward pull to carry the upper inward toward the edge of the last bottom.

136. In a machine of the class described, a gripper for engaging an upper on a last, means for closing said gripper on the upper and for swinging it in a direction to pull the upper outward from the edge of the last bottom, and controlling means constructed to cause the gripper in response to resistance of the upper in said outward pull to move bodily in a direction to draw the upper inward toward the edge of the last bottom.

137. In a machine of the class described, a gripper for engaging an upper on the last, a guide for said gripper inclined to the

plane of the last bottom, and gripper closing means constructed to swing the gripper in a direction to pull the upper outward from the edge of the last and then automatically by its continued pull upon the gripper to move the gripper bodily along said guide for further pulling the upper.

138. In a machine of the class described, a gripper for engaging an upper on a last comprising a pair of jaws pivoted together for relative opening and closing movements, a gripper support having a slot extending at an inclination to the plane of the last bottom, a pivot for said jaws positioned in said slot, an operating lever mounted on said pivot for closing the jaws, and means connected to said lever for operating it to close the gripper and swing it about said pivot and then to move the gripper bodily along said slot in pulling the upper.

139. In a machine of the class described, a gripper for engaging an upper on a last, and gripper operating means comprising an arm extending laterally outward from the gripper and mechanism connected to said arm for imparting an upper pulling movement to the gripper and for swinging the gripper outward with respect to the lateral surface of the last during said movement.

140. In a machine of the class described, a gripper for engaging an upper on a last, means for operating said gripper to pull the upper in a direction transverse to the plane of the last bottom, and a guide extending about said gripper and provided with an opening extending in a direction transverse to the direction of the pull of the gripper and affording provision for limited movement of the gripper in such transverse direction in response to the resistance of the upper.

141. In a machine of the class described, a gripper for engaging an upper on a last, means for operating said gripper to pull the upper, a guide extending about said gripper and provided with an opening affording provision for limited movement of the gripper in a direction transverse to the direction of the pull, and yieldable means arranged to bear frictionally on said gripper to limit its freedom of movement in the guide.

142. In a machine of the class described, a gripper for engaging an upper on a last comprising a pair of jaws pivoted together for relative opening and closing movements, operating means connected to one of said jaws for opening and closing it and for moving the gripper to pull the upper, and retarding means frictionally engaging the other jaw to render said operating means effecting in opening and closing the gripper.

143. In a machine of the class described, a gripper for engaging an upper on a last comprising a pair of jaws one of which is pivoted to the other for opening and closing

movements, operating means connected to said pivoted jaw for opening and closing it and for moving the gripper to pull the upper, and a relatively stationary guide extending about the gripper and provided with frictional retarding means for engaging the other gripper jaw to render said operating means effective in opening and closing the gripper.

144. In a machine of the class described, the combination with a toe gripper, of grippers for engaging an upper at opposite sides of a last at the rear of the toe gripper, said rear grippers being connected for movement together in the same direction laterally of a shoe and also mounted for movement to alter their angular relation to the longitudinal median line of the shoe to adapt them to operate respectively upon right and left shoes.

145. In a machine of the class described, the combination with a toe gripper, of grippers for engaging an upper at opposite sides of a last at the rear of the toe gripper, means for moving said rear grippers together laterally of a shoe to position them in different locations for operating respectively upon right and left shoes, and means for causing the rear grippers through said lateral movement to assume different angular relations to the longitudinal median line of the shoe.

146. In a machine of the class described, grippers for engaging an upper at opposite sides of a last, said grippers being connected for movement in unison laterally of a shoe and also mounted for movement to alter their angular relation to the longitudinal median line of the shoe to adapt them to operate respectively upon right and left shoes, and means for effecting also a relative bodily adjustment of said grippers toward and from each other.

147. In a machine of the class described, grippers for engaging an upper at opposite sides of a last, said grippers being mounted to swing about independent axes located substantially at opposite sides of the last at the rear of the toe end to position them differently for right and left shoes, and means for also relatively adjusting said grippers bodily toward and from each other.

148. In a machine of the class described, a rod arranged with its end in position to engage the bottom of a shoe to act as a sole rest, a gripper for engaging the upper of the shoe, and operating means movable along said rod for closing the gripper and for operating it to pull the upper.

149. In a machine of the class described, the combination with grippers for engaging an upper on a last and levers extending lengthwise of the last and connected to said grippers for operating them, of manually operated means extending laterally of the

shoe and connected to said levers for moving one of the levers in a direction to increase the tension of the upper and for simultaneously moving the other lever in a direction to relax the tension of the upper.

150. In a machine of the class described, the combination with grippers for engaging an upper on a last, of a manually rotatable shaft, and connections between said shaft and the grippers to cause one gripper to move in a direction to increase the tension of the upper and another gripper to move in a direction to relax the tension through a turning movement of said shaft in one direction.

151. In a machine of the class described, the combination with grippers for engaging an upper at opposite sides of a last and levers extending lengthwise of the last for operating said grippers, of manually operated means connected to said levers to move them simultaneously in opposite directions for shifting the upper transversely of the last.

152. In a machine of the class described, the combination with grippers for engaging an upper at opposite sides of a last and means for operating said grippers, of a rotatable shaft extending laterally of the shoe, and connections between said shaft and grippers for moving one of the grippers in a direction to increase the tension of the upper and the other in a direction to relax the tension through a turning movement of said shaft in one direction.

153. In a machine of the class described, the combination with grippers for engaging an upper at opposite sides of a last and levers for operating said grippers, of a rotatable shaft provided with eccentric portions, and connections between said eccentric portions of the shaft and said levers for moving the levers respectively in substantially opposite directions through a movement of the shaft in one direction.

154. In a machine of the class described, the combination with grippers for engaging an upper at opposite sides of a last, said grippers being mounted to swing lengthwise of the last, of a rotatable shaft extending laterally of the shoe and provided with eccentric portions connected to said grippers for moving them respectively in opposite directions lengthwise of the last.

155. In a machine of the class described, the combination with grippers for engaging an upper at opposite sides of a last, of gripper guides mounted to swing lengthwise of the last for adjusting said grippers, a rotatable shaft extending laterally of the shoe, and eccentric members on said shaft arranged to engage in slots in said guides for moving the different guides respectively in different directions lengthwise of the last.

156. In a machine of the class described, the combination with means for positioning

a last and an upper, of a member mounted to travel about an end of the shoe for laying the margin of the upper over the last, means for inserting fasteners to secure the upper in overlaid position, and means for moving said member toward the shoe bottom to increase the pressure upon the margin of the upper for each fastener inserting operation and for subsequently relieving the pressure to permit the member to be withdrawn.

157. In a machine of the class described, the combination with a wiper for working an upper over the bottom of a last and means for inserting a fastener to secure the upper, of means connected to the wiper and arranged to be operated by said fastener inserting means for pressing the wiper down upon the margin of the upper.

158. In a machine of the class described, the combination with a wiper and means for operating it to work the margin of an upper over the bottom of a last, of means for inserting a fastener to secure the upper, and additional means connected to said wiper for operating it in time relation to the fastener inserting means to press the upper down upon the margin of the shoe bottom and then to relieve the pressure.

159. A machine of the class described having, in combination, power operated means for pulling over a shoe in one position of the shoe, power operated means for lasting an end of the shoe when presented in a different position, and means constructed and arranged to support the shoe independently of the pulling-over means and to transfer the shoe from pulling-over to lasting position.

160. A machine of the class described having, in combination, means for pulling over a shoe in one position of the shoe, power operated means for lasting both the heel and toe ends of the shoe when presented in a different position, and shoe positioning means movable with the shoe from pulling-over to lasting position.

161. A machine of the class described having, in combination, means for pulling over a shoe in one position of the shoe, means for lasting both the heel and toe ends of the shoe when presented in a different position, and means automatically operative in time relation to the pulling-over and lasting means to transfer the shoe from pulling-over to lasting position.

162. In a machine of the class described, an upper engaging gripper comprising jaws pivoted together for relative closing and opening movements, and jaw closing means comprising a lever pivoted on one of said jaws and having wedging engagement with the other jaw.

163. In a machine of the class described, an upper engaging gripper comprising relatively movable jaws, jaw closing means

- comprising a lever arm adapted to extend outward from the gripper in transverse relation to the planes of the gripping faces of the jaws and in substantially rigid relation 5 to the gripper when the jaws are closed, and operating means connected to said arm for closing the jaws and for then operating the gripper to pull the upper, the gripper being free to swing outwardly from the lateral periphery of the last in response to the pull 10 of the operating means on said lever arm.
164. In a machine of the class described, the combination with last and upper positioning means, of a toe gripper, grippers 15 for engaging the upper at opposite sides of the last at the rear of said toe gripper, and means movable about an axis extending in transverse relation to the plane of the shoe bottom and located substantially at the toe end of the shoe to adjust said rear grippers laterally of the shoe.
165. In a machine of the class described, the combination with last and upper positioning means, of a toe gripper, side grippers, power means for operating said grippers to pull the upper, additional grippers for engaging the upper at the rear of said side grippers, and manual means for operating said additional grippers independently of the side grippers.
166. In a machine of the class described, the combination with last and upper positioning means, of a toe gripper, side grippers, and additional grippers arranged to engage and pull the upper at the rear of said side grippers, said additional grippers being adjustable relatively to the side grippers in directions lengthwise of the last and in different angular relations to the longitudinal median line of the last.
167. In a machine of the class described, the combination with last and upper positioning means, of a toe gripper, side grippers, additional grippers arranged to engage and pull the upper at the rear of said side grippers, and means for moving said additional grippers simultaneously in different respective directions lengthwise of the last and relatively to the side grippers 45 and for turning them during such movement to adjust their angular relation to the longitudinal median line of the last.
168. In a machine of the class described, the combination with last and upper positioning means, of a toe gripper, side grippers, additional grippers arranged to engage the upper at the rear of said side grippers, means for adjustably moving the side grippers and the additional grippers together laterally of the shoe, and means automatically operative in said lateral movement of the grippers to move said additional grippers respectively in different directions lengthwise of the shoe and relatively to the side grippers.
169. In a machine of the class described, the combination with last and upper positioning means, of a toe gripper, side grippers, additional grippers arranged to engage the upper at the rear of said side grippers, means for adjustably moving the side grippers and the additional grippers together laterally of the shoe, and means automatically operative in said lateral movement of the grippers to move said additional grippers in different respective directions lengthwise of the shoe and relatively to the side grippers and to turn said additional grippers to adjust the angular relation of their gripping faces to the longitudinal median line of the shoe.
170. In a machine of the class described, the combination with a gripper adjustably movable to position it relatively to a shoe, and means for operating said gripper to pull the upper, of a hold-down member mounted for adjusting movement with said gripper and relatively to which the gripper is movable to pull the upper, said member being arranged to engage the marginal portion of the sole of the shoe, and means for controlling said hold-down member to maintain it in engagement with the sole as the gripper is moved to pull the upper.
171. In a machine of the class described, the combination with a gripper for pulling an upper over a last, said gripper being mounted for movement along the plane of the shoe bottom, of a hold-down member associated with said gripper for movement with it along said plane and arranged to engage the marginal portion of the sole of the shoe, and means for moving said gripper and hold-down member in substantially opposite directions in the upper pulling operation.
172. In a machine of the class described, the combination with opposite side grippers movable to pull an upper over a last, said grippers being adjustable relatively to the shoe along the plane of the shoe bottom, of hold-down members adjustably movable with said grippers and arranged to engage the marginal portion of the sole of the shoe, and means for imparting to said hold-down members in the course of the upper pulling operation movement in a direction substantially opposite to the direction of the pull of the grippers.
173. In a machine of the class described, the combination with shoe positioning means, of upper pulling means comprising a gripper positioned relatively to said shoe positioning means to pull the upper at the inner side of the shoe in a location where the edge of the last bottom curves inwardly toward the shank, said gripper being mounted for turning movement about an axis substantially perpendicular to the bottom face of the last.
174. In a machine of the class described,

the combination with shoe positioning means, of upper pulling means comprising a gripper positioned relatively to said shoe positioning means to pull the upper at the inner side 5 of the shoe in a location where the edge of the last bottom curves inwardly toward the shank, and means for removing said gripper forwardly toward the toe end of the last and for simultaneously turning it about an 10 axis substantially perpendicular to the bottom face of the last.

175. In a machine of the class described, the combination with shoe positioning means, of upper pulling means comprising a gripper 15 for pulling the upper at the inner side of the shoe in a location where the edge of the last bottom curves inwardly toward the shank, said gripper being adjustable lengthwise of the shoe and about an axis substantially perpendicular to the bottom face of the last to position it for operating respectively on right and left shoes.

176. In a machine of the class described, the combination with shoe positioning means, 25 of upper pulling means comprising a gripper for pulling the upper at the inner side of the shoe in a location where the edge of the last bottom curves inwardly toward the shank, and a single means for imparting to 30 said gripper a bodily movement lengthwise of the shoe and a turning movement to position it differently for operating respectively on right and left shoes.

177. In a machine of the class described, 35 the combination with shoe positioning means, of grippers for pulling the upper at opposite sides of the last in locations where the edge of the last bottom curves inwardly toward the shank, said grippers being connected 40 for adjusting movements respectively in opposite directions lengthwise of the shoe and mounted for turning movements about axes substantially perpendicular to the bottom face of the last to position them differently 45 for operating respectively on right and left shoes.

178. In a machine of the class described, the combination with shoe positioning means, 50 of grippers for pulling the upper at opposite sides of the last in locations where the edge of the last bottom curves inwardly toward the shank, and means for adjusting said grippers to operate respectively on right and left shoes comprising mechanism for imparting 55 to the grippers turning movements in predetermined relation to each other about axes substantially perpendicular to the bottom face of the last.

179. In a machine of the class described, 60 the combination with shoe positioning means, of grippers for pulling the upper at opposite sides of the last in locations where the edge of the last bottom curves inwardly toward the shank, and means for moving said grippers respectively in opposite directions

lengthwise of the shoe and for imparting to them simultaneously turning movements about axes substantially perpendicular to the bottom face of the last to adjust them differently for operating respectively on right 70 and left shoes.

180. In a machine of the class described, the combination with shoe positioning means, of grippers for pulling the upper at opposite sides of the last in locations where the edge 75 of the last bottom curves inwardly toward the shank, means for moving said grippers together laterally of the shoe to position them differently for operating respectively on right and left shoes, and mechanism automatically operative in such movement of the grippers to move them respectively in opposite directions lengthwise of the shoe and to turn them about axes substantially perpendicular to the bottom face of the last. 85

181. In a machine of the class described, the combination with shoe positioning means, of upper pulling means comprising a gripper for pulling the upper at the side of the last, means for moving said gripper lengthwise of the last, and mechanism responsive to such movement of the gripper for imparting to it a turning movement about an axis substantially perpendicular to the bottom face of the last. 95

182. In a machine of the class described, the combination with shoe positioning means, of overlaying and fastening mechanism mounted to travel in a predetermined path along the edge of the shoe bottom about an 100 end of the shoe from one side of the shoe to the other to overlay and fasten the upper progressively, said mechanism being automatically operative in its movement about the end of the shoe to insert a plurality of 105 upper securing fastenings in succession.

183. In a machine of the class described, the combination with shoe positioning means, of overlaying and fastening mechanism comprising a wiper and a tacker mounted to 110 travel as a unit about an end of the shoe from one side of the shoe to the other, and means for imparting to said wiper and tacker respectively in their travel about the end of the shoe a plurality of overwiping 115 and tack driving movements.

184. In a machine of the class described, the combination with shoe positioning means, of a wiper and a tacker for overlaying and fastening the margin of the upper, said 120 tacker comprising a tack holder and a driver, means for moving said wiper inwardly and outwardly over the shoe, and mechanism responsive to the tack driving movement of the driver for imparting to the wiper a 125 movement relatively to the tack holder to press the margin of the upper upon the insole.

185. In a machine of the class described, the combination with shoe positioning means, 130

of end lasting mechanism comprising an overlaying member movable progressively about an end of the shoe to lay different portions of the margin of the upper successively over the insole, and means for controlling said overlaying member to position it in substantially the same angular relation to different successive portions of the edge of the shoe bottom in its travel about the end of the shoe. ¹⁰

In testimony whereof I have signed my name to this specification.

MARGARET B. STIGGINS,

*Executrix of the will of Edward A. Stiggins,
deceased.*
